TYPE SETTING MACHINES

Blackwell K. Murchison, Brooklyn, N. Y.; Bessie F. Murchison, executrix of said Blackwell K. Murchison, deceased

Application February 21, 1951, Serial No. 212,054

54 Claims. (Cl. 276—10)

This invention relates to new and useful improvements in type setting machines.

More particularly, the invention proposes a type setting machine which will set and justify the lines of type, working on one line at a time. It is proposed that this line be proof read, and then reproduced by any known process, such as printing, photography, casting, matrix making, stencil cutting, etc. The individual lines may be reproduced by various types of printing such as contact, photo-engraving reduced to size, black and white, photo-offset, etc. The printing may be done on white paper or other paper, or on thin transparent paper in which case contact transfers may be made by photo prints, blueprints, Ozalid process, Van Dyke process, etc. The new type setting machine will automatically redistribute the type of the line of type after it has been reproduced and then immediately set a new line.

It is proposed to provide the new type setting machine with type support rings into which the type, and wedges may be set. With this arrangement it is possible to set various kinds of type into the said rings for various methods of reproduction. The type may read from right to left, or from left to right; it may be placed in up side up, or up side down.

It is proposed to so construct the new type setting machine that it will be 100% automatic operating in a continuous cycle for setting and justifying each line of type and pausing for the reproduction of the line, then redistributing the type and automatically setting the next line. In order to make the machine 100% automatic it is proposed that several control units be used, one to operate a perforated tape which controls selecting the type face and pieces of type, and a second control unit to automatically restart the type setting machine when the reproduction of a line is completed.

It is contemplated to arrange the type support rings in axially aligned positions. A simple means is provided for rotatively supporting each of the rings. These rings are rotatively supported on a frame of the machine which includes a table top. It is proposed to provide a carriage slidably mounted on the table top and provided with a horizontal type carrier bar normally positioned across one of the sides of the said rings. A novel arrangement is provided for moving the carriage across the table top to a forward position and back again. Wheels rotatively mounted on the frame and positioned to the sides of the rings are connected with eccentric rods which connect with the carriage for moving the carriage forwards and rearwards. A cam shaft is rotatively mounted on the frame at a point beneath the table and extends parallel to the axes of the said rings. It is proposed to provide a pushout comb within the type support rings for pushing type and type wedges from the rings onto the type carrier bar. It is an object of this invention that said push out comb be operated by means controlled by a cam or cams on said cam shaft.

It is also contemplated to provide a type push back

2

comb movably mounted on the table top to the front of the carrier bar for pushing the type and type wedges back into the rings from the type carrier bar. It is an object herein that said push back comb be operated by means controlled by cams mounted on said cam shaft.

It is proposed that each of the type support rings be individually rotated by means including an electric motor. Another object herein is that novel means be provided for stopping each of said rings in a selected position in relation to said type carrier bar in order that any piece of type and type wedges carried by each of the rings may be stopped at the said bar. It is another object herein that novel means be provided for moving the type and type wedges stopped at said bar to a position on the bar.

It is contemplated to form the type support rings with radial slots for the type and type wedges, said slots extending from the inside diameters completely through to the outside diameters of the rings, and said slots being positioned at closely spaced points around the peripheries, 20 of the rings. These radial slots should be arranged with their wide portions transversely of the rings in order that a relatively large number of pieces of type and type wedges may be arranged around the peripheries of the rings while maintaining the rings at a minimum diameter.

25 A novel means should be provided for turning each of the pieces of type projected over the type carrier bar from sidewise positions to vertical positions in order to place them in proper positions for justifying. A strip should be mounted along the type carrier bar and should be engageable with slots formed in the bottom edges of the type and type wedges for securely holding the type and type wedges on the type carrier bar when the type and type wedges are turned into said vertical positions.

30 A novel means is also proposed for movably supporting the type and wedges on the type carrier bar in order that the type and wedges may be moved together into printing positions. A novel arrangement should be provided for controlling the type wedges for justifying each line of type.

35 It is also proposed to provide novel means for moving the type and type wedges together to a predetermined width which represents the maximum width of the line of type set.

40 It is also proposed to provide novel means for clamping the type and type wedges firmly in their justified positions for firmly holding the type during the reproduction process. This is particularly valuable if the reproduction process is one requiring contact and pressure with the type.

45 It is proposed to provide novel means for operating said clamping means controlled by cams on said cam shaft. An important object of this invention resides in mounting the type push back comb on a horizontal slide, which in turn should be mounted on a vertical slide so that the push back comb may be moved horizontally for pushing the type back when required, and may be moved vertically to a position below the table top in order to be out of the way to permit the carriage supporting the type carrier bar with type and type wedges to move to its front reproduction position.

50 Another object of this invention resides in the provision of novel means for operating said push back comb controlled by cams on said cam shaft.

55 Another object of the invention resides in the provision of a novel type spreading means for spreading out the type from the justified position back to their original positions so that the type may be reinserted into the slots of the type support rings. It is contemplated to characterize this novel type spreading means by an accordion-like structure having prongs which are engageable into slits formed in the tops of the type and type wedges.

It is also contemplated to provide a stationary comb into which the said prongs which engage the type may engage to assist in accurately returning the type to positions aligned with the radial slots in the type support rings.

Another object of this invention resides in the provision of compression slides mounted on the type carrier bar and provided with rollers engaging cam tracks in the table top of the type setting machine for guiding the compression of the type to the desired line size.

It is also contemplated to characterize the means which opens and closes the type wedges by a connector adapted to connect with slots formed in the rear ends of the type wedges. It is proposed to arrange this connector upon a horizontal slide, which in turn should be mounted on a vertical slide and by which the connector may be raised above the table top into operating position and moved below the table top when required in order to permit the carriage which supports the horizontal type carrier bar to move back and forth on the table.

Another object of this invention resides in the provision of a tape control unit through which perforated tape may pass and which controls the stopping of the rotation of the type support rings in pre-selected positions, depending on the perforations in said tape.

More particularly, it is proposed to perforate the tape with two transverse openings along each longitudinal line of the tape, one of these openings to control selection of the type face, and the other to control selection of the type and type wedges of the selected type face.

Another object of the invention resides in the specific construction of the tape control unit by which the tape may be easily engaged into and removed from its position in the control unit.

It is proposed to characterize the tape control unit by a tape guide front plate and a tape guide back plate which are moved relatively to each other by eccentric means controlled with a motor operating periodically during the operation of the control unit. More particularly, it is proposed that the tape move forward in steps, one step for each line of type to be set and for each step it is proposed that said eccentric action take place.

Another object of this invention resides in the provision of another control unit for restarting the type setting machine each time that the reproducing process used to reproduce the set line has been completed.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 79 is a fragmentary sectional view taken on the line 79—79 of Fig. 78.

Fig. 80 is a fragmentary enlarged sectional view taken on the line 80—80 of Fig. 78.

Fig. 81 is a portion of the schematic wiring diagram of the type setting machine showing particularly the wiring of the type support rings and associated parts.

Fig. 82 is another portion of the schematic wiring diagram showing particularly the perforated tape control unit. Fig. 82 must be placed against the right hand end of Fig. 81 to show the relationship of these two figures.

Fig. 83 is another portion of the schematic wiring of the machine showing particularly the wiring associated with the eccentric wheel shaft and cam shaft of the type setting machine. Fig. 83 must be placed against the bottom of Fig. 81 to show the relationship of these two figures.

Fig. 84 is a schematic view and wiring diagram of another control unit for providing time for printing, photographing or copying lines of type set by the type setting machine and which automatically controls the operation of the type setting machine. Fig. 84 must be placed against the right hand end of Fig. 83 to show the relationship of these figures.

Fig. 85 is a schematic figure indicating the timing of the cams and associated parts of the type setting machine and its controls.

The type setting machine, in accordance with this invention, includes a frame 30 consisting of a base 31, main sides 32, auxiliary sides 33, a drum 34, and a table top 35. The sides 32 and 33 are mounted on and attached to the base 31. The main sides 32 and the auxiliary sides 33 are secured together with a plurality of spacer rods 36. The main sides 32 are formed with circular openings 37 into which the ends of the drum 34 are engaged and fixedly mounted. The table top 35 is fixedly mounted across the tops of the auxiliary sides 33.

A plurality of adjacent axially aligned type support rings 38 are rotatively mounted on the frame 30, and more particularly, on the drum 34 thereof. Each of the type support rings 38 comprises an annular flat body which has an inside diameter 39 slightly larger than the outside diameter of said drum 34. Each type support ring 38 has an outside diameter 40, and flat sides. Radial slots 41 for type are positioned at closely spaced points around the circumferences of the type supporting rings 38 and extend radially from their inside to their outside diameters. Each type support ring 38 is rotatively supported on the drum 34 by a plurality of rollers 42 positioned at spaced points around the type support rings 38. These rollers 42 have their axes parallel to the axes of the rings 38. The drum 34 is formed with peripheral grooves 43 into which the rollers 42 engage. The rollers 42 are secured in position with brackets 44. The drum 34 is provided with stationary end rings 45 stationarily mounted upon the end portions of the drum 34. These end rings 45 are provided with a plurality of rollers 46 engaging against the adjacent flat faces of the adjacent rings 38. The rollers 46 are mounted on the inner faces of the stationary end rings 45. The rollers 46 have their axes radial of the drum 34.

A ring gear 47 is attached upon one of the sides of each of the type support rings 38. Additional rollers 48 are rotatively mounted at spaced points upon the inside diameters of each ring gear 47. These additional rollers 48 have their axes radial to the drum 34. They are supported by brackets 49. They serve to engage the adjacent face of an adjacent type support ring 38 to further assist in the rotative mountings of the rings 38.

In Fig. 42 a fragmentary edge portion of one of the rings 38 has been illustrated. It should be noted that the radial slots 41 are of rectangular shapes and are arranged

with their long dimensions transversely across the face of the ring 38. The purpose of arranging the slots 41 transversely is to make it possible to provide the rings 38 with a greater number of the slots 41. Type 54 and type wedges 55 are set into the slots 41.

The type wedges 55 are for the purpose of providing spaces between words formed by the type 54. They also serve to make it possible to justify the type. Each piece of type 54 and wedge 55 is provided with a leaf spring 56 mounted one one side for engaging against one face of the slots 41 for frictionally holding the type 54 and type wedges 55 in position in the slots 41.

A carriage 56, see Fig. 61, is slidably mounted on the frame 30, and more particularly, upon the table top 35. This carriage 56 is provided with a horizontal type carrier bar 57 normally positioned near one of the sides of the rings 38. The carriage 56 includes slides 58 upon which the horizontal type carrier bar 57 is rigidly attached. These slides 58 are formed with grooves 59 which engage tracks 60 mounted upon the sides of the table top 35.

A type holding strip 61 is mounted upon the top of the horizontal type carrier bar 57. This strip 61 is provided with a beveled edge 62 located at the side near the rings 38. The type 54 and the type wedges 55 are formed with notches 63 shaped to snugly engage upon the type holding strip 61. A vertical post 65 is fixedly mounted on each end portion of the horizontal type carrier bar 57. A type locking bar 66 is fixedly mounted across the posts 65 at a position slightly spaced above the type carrier bar 57. Each piece of type 54 and each type edge 55 is provided with a front stop lug 67 adapted to engage across the front bottom corner of the type locking bar 66 in order to securely hold the type 54 and wedges 55 on the type carrier bar 57. The type 54 and type wedges 55 must be moved through the space between the type carrier bar 57 and the type locking bar 66 in a sidewise position, and then must be turned around vertically so that the notches 63 engage the strip 61 while the lugs 67 engage against the front bottom corner of the type locking bar 66. The lugs 67 project over one of the ends of the openings 41 and in this way limit the "in" position of the type 54 and wedges 55 in the openings 41.

The rings 38 are associated with means by which they may be turned to selected positions in relation to the type carrier bar 57. This means includes for each ring 38, the said ring gear 47. A support bar 70 is mounted across the sides 32. The ends of the bar 70 are attached to blocks 71 which are attached to the sides 32. The bar 70 is provided with a downwardly extending central web 72 for stiffening it. There is a gear housing 73 for each type support ring 38. These gear housings 73 are fixedly mounted on the support bar 70. A shaft 74 is turnably mounted through each gear housing 73. Each shaft 74 is provided with a gear 75. Each gear 75 meshes with the ring gear 47 of its corresponding type support ring 38. It should be noted that the gear housings 73 are located across the bottom of the type support rings 38. A worm wheel 76 is mounted within each housing 73 and on each shaft 74. Each worm wheel 76 meshes with a worm 77 rotatively mounted in each gear housing 73. Each worm 77 connects with a flexible drive shaft 78. Each drive shaft 78 connects with a drive motor 80. These drive motors 80 are mounted on a group of shelves 81. The shelves 81 are supported by side brackets 82 which in turn are mounted on the base 31. With this construction each motor 80 drives one particular type support ring 38. There is one motor 80 for each of the type support rings 38. Therefore, each type support ring 38 is capable of being rotated by one of the motors 80.

The means for stopping each of the type support rings 38 in correct relation to the type carrier bar 57 will be given further on in this specification. When all of the type support rings 38 have been stopped in correct posi-

tion the next operation consists in pushing the type 54 and type wedges 55 which are aligned with the type carrier bar 57 out from the slots 41 of the type support rings 38 and into a position above the type carrier bar 57.

5 This pushing out means includes a type push out comb 83 positioned within the drum 34. This comb 83 has a back 84 and teeth 85. The front ends of the teeth 85 normally engage in openings 86' in the stationary drum 34 at positions aligned with said radial slots 41 of the type support rings 38. The back 84 of the comb 83 extends completely longitudinally through the drum 34 and its ends slidably engage through slots 86 in brackets 87 mounted on horizontal support bars 88 which are mounted across the sides 32 in the vicinity of the horizontal center of the drum 34. A bracket 89 is attached to each of the bars 88. These brackets 89 support guide pins 90. An arm 91 is provided for each end of the comb rack 84. These arms 91 have one of their ends pivotally connected with the comb back 84 by pintles 92.

10 The arms 91 have their other ends pivotally connected by pintles 93 with the ends of rods 94 which slidably engage through the guide pins 90. The other ends of the rods 94 support fins 95 which are pivotally connected with guide arms 96. These guide arms 96 are pivotally supported at their bottom ends by pintles 97 upon the sides 33. The guide arms 96 are pivotally connected with the fins 95 by pintles 98 which support followers 99 engaging cam tracks 100 formed in cams 101. The cams 101 are mounted upon the end portions of a cam shaft 102 which is rotatively supported by bearings 103 mounted on the sides 33. The cam shaft 102 is provided with a gear 104 which meshes with a pinion 105 of a gear reduction unit 106 which is driven by a motor 107. Each of the cam tracks 100 has a section 108 which will cause the rods 94 to be moved towards the right in order to move the arms 91 towards the right and in this way correspondingly move the comb 83. In Fig. 26 the comb 83 is shown in its extreme left position in which the type support rings 38 are free to rotate. In Figs. 46 and 47 the comb 83 is shown in its extreme right position in which the type 54 and type wedges 55 have been pushed out from the slots 41 of the type support rings 38. The tracks 100 of the cams 101 are also provided with sections 109 which are used to move the comb 83 back to its left position.

15 Means is provided for supporting the type 54 and the wedges 55 in horizontal positions when they are pushed out from the type support rings 38. This means includes a strip 112 extending along one of the sides of said type support rings 38 in a position between said support rings 38 and the horizontal type carrier bar 57. This strip 112 extends parallel to the type carrier bar 57. It is slightly higher than the type carrier bar 57 and is secured along its bottom edge by fastening elements 113 to the edge 20 of the table top 35. A plurality of flanged discs 114 are rotatively mounted along the length of the strip 112.

25 The discs 114 have flanges which engage the faces of the strip 112. There is one disc 114 for each of the type support rings 38. Each disc 114 is provided with a rectangular opening 115 which is normally disposed in a horizontal position aligned with the type slots 41 from which the type 54 and wedges 55 are pushed by the comb 83. Each disc 114 is provided with a pair of adjacent balls 117 (see Fig. 60) acting to clamp the type 30 54 or wedge 55 pushed into the rectangular opening 115. Each ball 117 is urged into clamping position by a spring 118 mounted in the disc 114. Normally, the balls 117 of each disc 114 touch each other along the longitudinal center line of the rectangular opening 115 of the disc 114.

35 Each disc 114 is provided with a radial arm 120. These radial arms 120 project from one of the flanges of each of the discs 114. A bar 121 is slidably mounted on the strip 112 and extends adjacent the radial arms 120. This bar 121 is set into a groove 122 in one face of the strip 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970

75 112. This groove 122 serves to slidably support the

bar 121. A pin 123 projects from the bar 121 for each of the discs 114. These pins 123 engage in elongated slots 124 formed in the radial arms 120. The radial arms 120 are normally positioned at an angle of 45° to the horizontal see Fig. 35. In this position of the bar 121 the rectangular openings 115 are horizontal, as for example illustrated in Fig. 35. The bar 121 may be shifted towards the right to turn the discs 114 to positions in which the rectangular openings 115 are vertical, as for example illustrated in Figs. 53 and 60.

A slide 125 is slidably mounted on the table 35 and extends through a cutout 126 formed in the strip 112. This slide 125 has a fork 127 at one side which engages a finger 128 projecting downwards from the bar 121. The other side of the slide 125 is provided with a cutout 129 which is engaged by one end of a bell crank 130. This bell crank 130 is pivotally supported by a pintle 131 upon a bracket 132 which is supported on one of the spacer rods 36. The bell crank 130 is pivotal in a plane parallel to the strip 112. The slide 125 is slidable in this same direction. The other arm of the bell crank 130 is engaged by the forked end 133 of an arm 134 which is supported at its end 135 upon one of the spacer rods 36. This arm 135 is disposed at right angles to the bell crank 130. The arm 134 is provided with a follower 137 which engages a cam track 138 on a cam 139 which is mounted on said cam shaft 102. In Fig. 31 the cam track 138 is shown holding the follower 137 in a raised position, in which position the rectangular openings 115 are horizontal. This cam track 138 has a section which will move the arm 134 downwards for pivoting the bell crank 130, which in turn will move the slide 125 for moving the bar 121 so as to pivot the discs 114 through substantially 90° to turn the rectangular openings 115 into their vertical positions.

Particular attention is called to Fig. 46 in which the pushout comb 83 is illustrated in a position in which the type 54 and wedges 55 have been pushed out from the type support rings 38 and are being supported horizontally by the rectangular openings 115. The supported type 54 and wedges 55 are supported in a position extending over the horizontal type carrier bar 57. In this position, the lugs 67 of the type 54 and wedges 55 are aligned with the front edge of the locking bar 66 while the cutouts 63 of the type 54 and wedges 55 are aligned with the bar 61. When the type 54 and wedges 55 are turned upright, the cutouts 63 will mate with the bar 61 and simultaneously the lugs 67 will engage the front corners of the locking bars 66. The type 54 and wedges 55 are therefore held securely on the type carrier bar 57.

At one stage of the operation of the type setting machine, the type 54 and wedges 55 are pushed back from their position on the type carrier bar 57 to their original positions in the radial slots 41 of the type support rings 38. The type 54 and wedges 55 are first turned from their vertical positions on the type carrier bar 57 to horizontal positions, by the flanged discs 114 and the mechanism which turns these discs. The pushing back operation is accomplished with a push back comb 142. This comb 142 includes a comb back 143 and a series of horizontal teeth 144. The comb back 143 is in the nature of a vertical flat back which is fixedly mounted at its bottom edge portion upon a horizontal slide 145. The horizontal teeth 144 are mounted along the top edge portion of the back 143. There is one tooth 144 for each of the type pieces to be pushed back. The front ends of the teeth 144 rest upon and are supported by a support bar 146. This bar 146 is mounted at its bottom upon a vertical slide 147. The comb back 143 and the support 146 project through an opening 148 formed in the table top 35. The operation of the comb 142 includes a horizontal movement by which the type is moved back to the type support rings 38, and also a vertical movement by which the push back comb 142 is moved down beneath the table top 35 out of the way to make way for the

forward motion of the type carrier bar 57 as will be hereinafter more fully described.

The horizontal slide 145 is provided with side slide members 149 which slidably engage upon the edges of the vertical slide 147. The vertical slide 147 has side portions 150 provided with side lugs 151 which slidably engage upon vertical guide pins 152. These vertical guide pins 152 are mounted at their top ends upon the bottom face of the table top 35. The horizontal slide 145 is provided with elongated slots 153 through which the vertical guide pins 152 engage. These slots 153 permit the horizontal slide 145 to move freely forwards and back again. The horizontal slide 145 is also provided with a cutout 154 the sides of which straddle the ends of the support 146 when the push back comb 142 moves to its forward position.

The vertical slide 147 is associated with means for raising and lowering it. This means includes a pair of cams 155 mounted upon the cam shaft 102. These cams 155 are positioned near the sides 33 of the machine. Each cam 155 is provided with a cam groove 156 which is engaged by a follower roller 157. Each follower roller 157 is mounted upon an arm 158. Each arm 158 is pivotally mounted at one end upon one of the spacer rods 36. The other ends of the arms 158 are provided with pintles 159 by which they are pivotally connected with the lugs 151. In Fig. 27 the vertical slide 147 is shown in its raised position. The cam grooves 156 have sections 160 which maintain the vertical slide 147 in its raised position, sections 161 which serve to lower and raise the vertical slide 147 respectively, and sections 162 which maintain the vertical slide 147 in its lowered position.

The horizontal slide 145 is associated with means for moving it forwards and then back again. This means includes a pair of cams 163 mounted on the cam shaft 102 at positions near the outside faces of the sides 33. Each cam 163 is provided with a cam groove 164. A follower 165 engages each cam groove 164. Each follower 165 is mounted on a vane 166 which connects with a rod 167. Each rod 167 is slidably mounted through one of the guide pins 90. Each vane 166 is supported and guided by an arm 168 which are pivotally mounted at their bottom ends by said pintles 97 attached upon the sides 33. The outer ends of the rods 167 are provided with brackets 170 to which fins 171 are pivotally connected. These fins 171 pivotally connected with rods 172 which have their other ends pivotally connected by pintles 173 with the sides of the slides 149 of the horizontal slide 145. Each of the cam grooves 164 has a section 174 which maintains the push back comb 142 in its rear position. These sections 174 connect with sections 175 and 176 which act to move the push back comb 142 to its forward position and back again during the rotation of the cam shaft 102.

When the discs 114 turn the type 54 and the type wedges 55 upright, the balls 117 hold the type and wedges in substantially vertical positions, as illustrated in Fig. 60. It is necessary that the type 54 and type wedges 55 be moved to true vertical positions. This is accomplished with means for aligning said type into true vertical positions. This means includes side brackets 180 mounted upon the sides of the table top 35 at positions to the sides of the bar 112. An angle iron 181 is mounted across the tops of the side brackets 180 to rigidly hold them in position. A rod 182 is turnably mounted across the side brackets 180 at a position above the bar 112. Type aligners 183 are loosely mounted on the rod 182 and come in adjacent pairs which are provided with beveled bottom ends 184 which together form inverted U-shaped grooves. These inverted V-shaped grooves are located directly above the type 54 and type wedges 55 when the latter are in their upright positions. The centers of these V-shaped grooves are directly along the vertical center lines of the elongated openings 115 when the latter are in

their upright positions. There is a pair of type aligners 183 for each of the discs 114. The type wedges 55 are slightly wider than the type 54 and for this reason one of the top edges of the type wedges 55 is formed with a beveled section 185 at the point where the type aligners 183 will engage the type wedges 55. Each type aligner 183 has a slot 183a loosely engaged by a radial pin 183b mounted on said rod 182. The front end of each type aligner 183 is resiliently urged downwards by an expansion spring 183c acting between the type aligner 183 and the angle iron 181. The type aligners 183 are moved downwards by the springs 183c when the rod 182 is turned slightly clockwise in relation to Fig. 41, and the type aligners 183 will then engage the top edges of the type 54 and the type wedges 55 and align them into true vertical positions.

Means is provided for automatically turning the rod 182 as required to operate the type aligners 183. This means includes radial arms 186 upon the ends of the rod 182 and located at positions adjacently outside of the brackets 180. The radial arms 186 pivotally connect with connector rods 187 which are pivotally connected at their bottom ends with one of the arms 188 of bell cranks having the second arms 189. Said bell cranks are pivotally supported by pintles 189a mounted on blocks 217 which are mounted upon the sides 33. The arms 189 are provided with followers 190 which engage cam grooves 191 in cams 192 fixed upon the cam shaft 192. Each cam groove 191 has a section 193 which indirectly holds the type aligners 183 in their raised inoperative positions by engaging the pins 183b against the bottom ends of the slots 183a and therefore compressing the springs 183c. Each cam groove 191 has a section 194 which pivots the bell crank 189, 188 so as to move the connector rods 187 upwards and move the arms 186 to pivot the rod 182 so that the pins 183b move upwards in the slots 183a allowing the springs 183c to move the type aligners 183 into their downward operative positions.

Each piece of type 54 and each wedge 55 is provided with a top slot 196 by which they may be fixedly held in their vertical positions. These slots 196 are engageable by prongs 197 which slide between adjacent pairs of the type aligners 183 and which extend upwards through slots 198 in the angle iron 181. These prongs 197 connect with a series of leaf springs 199. The leaf springs 199 are arranged in adjacent pairs, one pair for each of the prongs 197. Each of the leaf springs 199 is of rectangular shape. Each of the adjacent pairs of the leaf springs 199 are connected together at their tops and bottoms with interengaging prongs 200. They are connected together at their sides with inter-engaging prongs 201. The leaf springs 199 are provided with openings 202 through which a supporting rod 203 passes. The leaf springs 199 are adapted to slide on the rod 203 so that they may open and close similar to the opening and closing of a bellows or an accordion. The ends of the rod 203 engage into side brackets 204 which are fixedly supported upon the top ends of the rods 65. The side brackets 204 are provided with vertical elongated slots 205 into which the ends of the rod 203 engages. Pegs 206 are mounted upon the ends of the rod 203 and extend upwards and are guided through an opening 207 formed in a screw 208 mounted on each of the brackets 204. Springs 209 are mounted on the pegs 206 and act between the screws 208 and the tops of the ends of the rod 203 for resiliently urging the rod 203 downwards into the bottom ends of the vertical slots 205.

Push rods 210 are mounted at their top ends on the end portions of the rod 203 and slidably extend downwards through the brackets 204. These rods 210 slidably engage through openings 211 formed in the end portions of the type carrier bar 57 and through the tracks 58. Brackets 212 are attached to the table top 35 in the vicinity of the bottom ends of the rods 210 when

the carriage 56 is in its starting position. Guide pins 213 are mounted on the brackets 212. A pusher rod 214 slidably engages through each guide pin 213. These pusher rods 214 pivotally connect with radial arms 215 which are mounted upon the outer ends of rods 216. These rods 216 are pivotally mounted through said blocks 217 mounted upon the sides 33. Radial arms 218 are fixedly mounted upon the inner ends of the rods 216. The outer ends of these radial arms 218 are provided with followers 219 which engage cam grooves 220 formed in cams 221 mounted upon the cam shaft 102. Each cam groove 220 has a section 222 which holds each radial arm 218 in a down position. In these down positions the push rods 210 are held raised so as to hold the rod 203 in a raised position in which the prongs 197 are in their elevated positions. The cam grooves 220 have sections 223 which pivot the radial arms 218 upwards so as indirectly to move the pusher rods 214 downwards so that the springs 209 may move the rod 203 downwards in order to move the leaf springs 199 downwards and in this way move the prongs 197 down into the slots 196 of the type 50 and the type wedges 55, which will serve to hold the type and type wedges in their aligned vertical positions. Fig. 40 illustrates the rod 203 in its raised position, while Fig. 51 illustrates it in its lowered position.

Each wedge 55 when in its upright position is composed of a pair of adjacent wedge sections 227 and 228. These sections 227 and 228 have parallel outer faces and inclined adjacent faces. They are slidably connected at their adjacent faces with a dovetailed connection 229. When the wedge sections 227 and 228 are moved to their pushed together (their contracted) positions the wedge 55 is thickest or expanded. The sections 227 and 228 may be pulled apart or expanded, as shown in Fig. 45 to make the wedge thin or contracted. Each wedge section 227 is provided with a tail portion 230 formed with a slot 231 in its bottom edge. The wedges 55 when stored in the radial slots 41 of the type support rings 38 are in their contracted positions.

When the type push out comb 83 pushes the type 54 and wedges 55 out from the radial slots 41 the wedges 55 are still in contracted positions. They remain in this condition until after the prongs 197 of the leaf springs 199 are pushed into the slots 196 of the type 54 and wedges 55. At this point of the operation of the machine, a wedge stretch out comb 232 is pushed into operative position. This web stretch-out comb 232 comprises a back 233 in the form of a vertical strip and a plurality of vertical pegs 234. The back 233 is positioned upon its bottom edge upon the table top 35 at a point directly adjacent the strip 112, between the said strip 112 and the type carrier bar 57. The end portions of the back 233 engage into vertical slots 235 formed in the brackets 180. These vertical slots 235 serve to guide the back 233 to move vertically upwards and downwards. A vertical pin 236 is fixedly mounted in each end portion of the back 233 and slidably engage vertical openings 237 formed in the brackets 180. Expansion springs 238 are mounted upon the pins 236 and act between the tops of the slots 235 and the back 233 for resiliently urging the back 233 into a down position resting on the top of the table top 35. Small end plates 239 are mounted upon the end of the back 233 and are located within the slots 235 for guiding the back 233.

There is one vertical peg 234 for each of the pieces of type 54 and the wedges 55. These vertical pegs 234 are positioned adjacent the discs 114. The pegs 234 normally project slightly above the top edge of the back 233. Each peg 234 has a head 240 at its bottom end which slidably engages in an opening 241 in said back 233. These openings 241 are formed upwards from the bottom edge of the back 233. Plugs 242 threadably engage in the openings 241 and hold expansion

springs 243 in position within the openings 241. These springs 243 act between the plugs 242 and the bottom heads 240 of the pegs 234 for resiliently urging the pegs 234 into their projecting positions.

A top horizontal stop strip 244 is mounted upon the strip 112 above the pegs 234 and forms a stop for the type 54 and wedges 55 during upward motion of the wedge stretch-out comb 232 as hereinafter further explained.

The wedge stretch-out comb 232 is associated with means for moving it into its raised position. This means includes a pair of cams 245 mounted upon the cam shaft 102. Each cam 245 is provided with a cam track 246 in which a follower 247 engages. Each follower 247 is mounted on an arm 248 which is pivotally mounted at one end 249 upon one of the spacer rods 36. The other ends of the arms 248 are provided with vertical rods 250 which are pivotally connected with the arms 248. These rods 250 extend upwards and have their top ends engaging into openings 251 formed in the table top 35. These openings 251 are arranged at spaced points near the end portions of the back 233. The cam track 246 is provided with a section 252 which serves to hold each of the arms 248 in a lowered position. Each cam track 246 is also provided with a section 253 which acts to raise and lower each arm 248 so as to raise the wedge stretch-out comb 232 and thereafter release it.

The end portions of the back 233 are provided with latches for latching the wedge stretch-out comb 232 in its raised position. Each of these latches comprises a horizontally slidable bolt 254 slidably mounted in the bottom portions of the ends of the back 233. These bolts 254 are resiliently urged outwards by springs 255. The outer ends of the bolts 254 are provided with reduced end portions 256. These end portions 256 normally engage against cam edges 257 formed on the slides 58. Directly above these cam edges 257 the slides 58 are provided with keeper plates 258. When the wedge stretch-out comb 232 is moved to its raised position the springs 255 will extend the bolts 254 so that the reduced ends 256 engage upon the top faces of the keeper plates 258. Now the wedge stretch-out comb is locked in its raised position. The wedge stretch-out comb 232 is released when the slides 58 move forwards so as to drop the bolts 254. The springs 238 then move the wedge stretch-out comb 232 to its bottom position. Later on when the slides 58 return to their original positions the cam faces 257 will engage the tops of the bolts 254 and force them back into the ends of the back 233 compressing the springs 255. When the wedge stretch-out comb 232 is raised the vertical pegs 234 will engage against the bottom of the type 54 and type wedges 55. Those vertical pegs 234 which engage type 54 are merely depressed against the raising action of the springs 243. Those vertical pegs 234 which engage type wedges 55 will engage into the slots 231 of the type wedges 55.

When the carriage 56 moves forwards it will carry along the type 54 and type wedges 55 which are mounted on the type carrier bar 57. The type wedges 55 now become expanded, see Fig. 54, because the vertical pegs 234 engage the slots 231 holding the sections 227 of the wedges stationary while the front sections 228 move forwards. At this point it may be well to point out that it is necessary for the type aligners 183 to be lifted free of the type 54 and type wedges 55 before the carriage 56 moves forwards. The cams 192 perform this function.

After the carriage 56 has moved forwards a small amount the reduced end portions 256 are freed from the keeper plates 258 which moves along with the carriage 56. This releases the comb 232 which is then moved back into its normal down position by the springs 238. In its down position the vertical pegs 234 disengage from the type wedges 55 which are now expanded and free. The carriage 56 is now free to move forwards to its

complete forward position. The means for moving the carriage 56 to its complete forward position includes a pair of side arms 260 which are pivotally mounted at one of their ends by pintles 261 to the sides of the slides

5 58. The other ends of the side arms 260 are pivotally connected by pintles 262 eccentrically on wheels 263. These wheels 263 are mounted on a shaft 264 rotatively mounted across the horizontal support bars 88. The shaft 264 extends through the drum 34. One of the wheels 263 is engaged by a drive belt 265 which connects with a pulley 266 mounted on the shaft 267 which is rotatively supported on one of the main sides 32. Another pulley 268 is mounted on this shaft 267 and is engaged by a belt 269 which is driven by an electric motor 270. When the wheels 263 are in the positions indicated in Figs. 1 and 2 the carriage 56 is in its rear position. After the wheels 263 have turned through 180° the carriage 56 will be in its forward position.

During the forward motion of the carriage 56 from its rear position to its complete forward position, the type 54 and type wedges 55 will be moved together into face contacting positions. The means for accomplishing this includes a pair of compression slides 271 slidably mounted on the type carrier bar 57. These slides 271 are arranged near the end portions of the carrier bar 57. Each slide 271 is provided with a horizontal ball bearing wheel 272 mounted on its bottom and engaging in a cam track 273 formed in the table top 35. These cam tracks 273 have short longitudinally extending portions 274 at their rear ends while the remaining portions of these tracks converge towards each other towards the front end of the table top 35. Their front ends 275 are spaced from each other a distance required to position the slides 271 for holding the type in a space 35 for the width of a line of type to be set.

Each of the compression slides 271 is provided with an upwardly extending wall portion 276 formed with a vertical slot 277 through which the supporting rod 203 of the series of leaf springs 199 engage. When the cam tracks 40 273 move the slides 271 together the wall portions 276 compress the leaf springs 199 so that the prongs 197 which engage the slots 196 of the type 54 and the type wedges 55, move the type and type wedges together. The series of leaf springs 199 are correctly guided into expanded positions when the carriage 56 returns to its rear position by a comb 280 which is mounted upon the horizontal bottom arm of the angle iron 181. The teeth of this comb 280 have rounded points 281 into which the leaf springs 199 engage. These teeth guide the springs 199 back to their original positions into guide slots 198 formed in the bottom arm of the angle iron 181. When the leaf springs 199 return to these slots 198 the type 54 and type wedges 55 will be in correct positions to be re-engaged into rectangular openings 115 of the discs 114.

55 After the carriage 56 has reached its complete forward position the type 54 and type wedges 55 will be fully compressed to the width of a line (see Fig. 55). It is now necessary that the type wedges 55 be expanded. Up to this point the type wedge closing mechanism which expands the wedges has been in a down position, as for example, shown in Fig. 5. It must now be raised to its up position as shown in Fig. 56. The type wedge closing mechanism includes a connector 285 for connecting with the rear ends of the type wedges 55. This connector is 60 in the form of a strip of material having an upwardly extending flange 286 which is adapted to engage into the slots 231 in the bottom faces of the type wedges 55. The connector 285 is supported upon a pair of parallel rods 287 which slidably engage through a yoke 288. The rods 287 have heads 289 upon their free ends. Expansion springs 290 are mounted on the rods 287 and act between the connector 285 and the yoke 288 for urging the connector 285 into a forward position in which the heads 289 engage the back face of the yoke 288.

75 The yoke 288 is fixedly mounted on a horizontal slide

291. This horizontal slide includes a horizontal plate 292 provided with side slides 293 along its side edges. These slides 293 slidably engage upon a second horizontal plate 294. This second horizontal plate 294 forms a part of a vertical slide 295. This vertical slide 295 includes said horizontal plate 294 supported by a pair of vertical side panels 296. These vertical side panels 296 are vertically slidably mounted upon a pair of vertical rods 297 mounted between the base 31 and the table top 35. The horizontal plate 291 is provided with elongated slots 298 through which the vertical rods 297 pass in order that the horizontal slide 291 is free to move forwards and rearwards. The vertical slide 295 is free to move upwards and downwards.

The vertical slide 295 is associated with means for moving it upwards to a position in which said connector 285 engages the slots 231 of the type wedges 55. This means includes a cam 300 mounted on the cam shaft 102. The cam 300 is provided with a cam groove 301 engaged by a follower roller 302 mounted on a web 303 mounted on the bottom of the horizontal plate 294. The cam track 301 has a section 304 which maintains the vertical slide 295 in its down position, and this section connects with a section 305 which raises the vertical slide 295 to its up position and holds it in this position for a certain period of time and then moves it down again to its bottom position. The horizontal slide 291 is associated with means for moving it forwards and rearwards. This means includes a boss 306 on the base 31. A pair of vertically extending arms 307 are pivotally mounted at their bottom ends by pintles 308 to the sides of the boss 306. These arms 307 extend upwards past the sides of the slides 293. Pintles 309 are mounted on the slides 293 and extend through vertical slots 310 formed in the top ends of the arms 307. The arms 307 are provided with follower rollers 311 which engage cam tracks 312 upon cams 313 which are mounted upon the cam shaft 102. The cam tracks 312 have sections 314 which hold the horizontal slide 291 in its rearward position. The track sections 314 connect with track sections 315 which act to move the horizontal slide 291 forwards and then maintain it in this forward position for a short period of time, and then move it back again to its rear position. Fig. 38 illustrates the wedge closing mechanism in its down position, while Fig. 56 illustrates it in its up position with the connector 285 engaging the wedge 55. Forward motion of the horizontal slide 291 causes the yoke 288 to move forwards, compressing springs 290 and providing the necessary pressure for forcing the wedge sections 227 forwards to expand the wedges, and in this way justify the type in the space allotted to it. When the horizontal slide 291 subsequently moves back to its rear position the wedge sections 227 will be pulled rearwards in order to return the wedges 55 into their contracted positions.

When the type 54 and type wedges 55 are in their forward positions, with the type wedges 55 expanded, the type 54 is clamped fixedly in this position so that it is ready for printing or for any other process or method of reproduction used in conjunction with the type setting machine. The clamping means operates in conjunction with the flexible locking bar 66. Cams 316 are arranged to force the central portion of the flexible locking bar 66 downwards in order to clamp the type 54 and type wedges 55 in position upon said type carrier bar 57. The cams 316 are associated with means by which they may be turned into and out of locking position. This means includes a rod 317 upon which the cams 316 are mounted. The rod 317 is turnably mounted in a pair of brackets 318 mounted on the table top 35. The ends of the rod 317 are provided with arms 319 by which the rod 317 may be turned. The arms 319 normally extend substantially horizontally and pivotally connect with vertical arms 320. A collar 321 is slidably mounted on each vertical arm 320. An expansion spring 322 is slidably mounted on each vertical arm 320 beneath each collar 321. Nuts 323 are mounted

on the vertical arms 320 to form bottom abutments for the springs 322. The collars 321 pivotally connect with arms 324 which are pivotally supported by being fixed on pintles 325 which engage through the sides 33. These pintles 325 are provided with rigid arms 326 which support followers 327 engaging cam tracks 328 on cams 329 mounted upon the cam shaft 102.

The cam tracks 328 have sections 330 for holding the vertical arm 320 in a raised position in which the cams 316 are inoperative. The collars 321 engage flanges 332 on the vertical rods 320 by which the vertical rods 320 may be held in vertical positions. The cam tracks 328 are also provided with sections 333 which function to pivot the arms 326 and so indirectly pivot the arms 324 to move the collars 321 downwards in order to compress the springs 322 and transfer pressure to the vertical arms 320 to move them downwards and in this way cause the arms 319 to turn the rod 317 in order to turn the cams 316 into locking positions in which the flexible locking bar 66 is flexed downwards against the top of the type 54 and the type wedges 55 to clamp them in fixed positions.

A counter-pressure fin 334 is mounted upon the vertical slide 295. This counter-pressure fin 334 has a bottom cutout portion 335 to make room for the horizontal plate 292 of the horizontal slide 291 to move. The horizontal plate 292 is formed with a cutout 336 to accommodate the end portion of the counter-pressure fin 334. In the raised position of the vertical slide 295 the front end of the counter-pressure fin 334 engages against the type carrier bar 57 illustrated in Fig. 56, in order to reinforce the type carrier bar 57 and prevent it from bending slightly rearwards during the application of printing pressure against the faces of the type 54. The table top 35 has an opening 337 through which the fin 334, the yoke 288 and the parts carried by said yoke 288 extend only when the wedge closing mechanism is in its up position. At other times these parts are below the table top 35 in order that the carriage 56 may travel across said table top 35 without interference from the wedge closing mechanism.

Each type support ring 38 is rotated by one of said motors 80. The means for stopping each of these rings 38 in correct relationship to the horizontal type carrier bar 57 includes a panel board 340. This panel board is vertically supported at one end of the base 31 by a frame which includes side bars 341. These side bars 341 are attached to angle members 342 mounted along the sides of the panel 340. The other ends of the side bars 341 are attached to the upper ends of uprights 343 adjacent to and attached to the sides 32. A cross bar 344 is mounted between the side bars 341. The panel 340 is provided with a horizontal line of openings 345, there being one opening 345 for each type support ring 38. For each type support ring 38 there is a bell crank 346. Each bell crank 346 is pivotally mounted at its center 347 upon a bracket 348 attached to the panel 340. A pusher rod 349 pivotally connects with one of the arms of each bell crank 346 and extends forwards and slidably engages through the cross bar 344. Each pusher rod 349 is formed from several sections, namely, a front section 350 which is pivotally connected with a central section 351, in turn connected with a rear section 352 which pivotally connects with the back arm of the bell crank 346. A rack brake section segment 353 is mounted on the front end of each section 350 and each segment 353 is positioned adjacent a gear ring 47 of a type support ring 38. The rear end of each bell crank 346 pivotally connects with a rod 354 which is connected with the core 355 of a solenoid 356. These solenoids 356 are mounted upon the panel 340. The rods 354 are of different lengths as required to connect the cores of the solenoids 356 with the bell cranks 346. When the cores 355 of the solenoids 356 are moved by energization of the solenoids 356 the motions are transmitted to the rack brake segments 353 which move forwards and engage the teeth

of the gear rings 47 and in this way lock the type support rings 38 in selected stationary positions. The control of the solenoids 356 will be hereafter fully described.

For each type support ring 38 there is a group of stationary contacts 360. These stationary contacts 360 are mounted on arcuate contact support members 361. These members 361 extend along portions of the circumferences of the type support rings 38. The members 361 are mounted at their ends upon rods 362 which are mounted across the stationary end rings 45. The rods 362 run parallel to the axis of the type support rings 38. A bar 363 is also mounted across the side stationary end rings 45 at a short distance from one of the rods 362. This bar 363 supports a cable 364. This cable 364 has its individual wires connected with the stationary contacts 360, as will be fully amplified hereafter when referring to the wiring of the machine.

The particular type setting machine illustrated in the drawings show each of the type support rings 38 designed to contain six different faces of type. For this reason each type support ring 38 is provided with six brushes 365 arranged around its outer circumference at points equally spaced from each other. Each brush 365 is urged outwards by a spring 366. The brushes 365 are held from being completely ejected by a stop member 367. Each type support ring 38 is provided with two accurate contact rails 363' and 364', respectively. These rails are arranged at slightly spaced radial distances of each other. These rails 363' and 364' extend through arcuate distances of approximately 60°, see particularly Fig. 81. For each type support ring 38 there are three contact arms 365' for engaging the rail 364', and three contact arms 366' for engaging the rail 363'. These contact arms 365' and 366' are stationarily mounted upon the drum 34. Within the drum 34 there are a plurality of supports 367'. The contact arms 365' and 366' are mounted on these supports 367' and extend through openings 368 in the drum 34 and in this way reach the arcuate contact rings 363' and 364'.

The shaft 264 supports two small cams 370 and 371 which respectively control switches 372 and 373 mounted on a block 374 supported on one of the horizontal support bars 88. The shaft 102 is provided with four small cams 374, 375, 376 and 377 which control four switches 378, 379, 381 and 380, respectively. These four switches are supported upon a support member 382 mounted on one of the spacer rods 36. The purpose and operation of these cams and switches will be given in detail later during the disclosure of the electric wiring of the machine.

One of the control units of the machine includes a frame 385 having a top 386, sides 387, and a bottom 388. This frame also has a horizontal partition 389 spaced a short distance above the bottom 388. A back insulation plate 390 is mounted on the back of the frame 385 and extends between the top 386, the partition 389, and across the sides 387. A front insulation plate 392 is mounted across the frame 385, and extends between the top 386, the sides 387, and the partition 389. This front plate 392 is composed of a plurality of horizontal insulation strips 393 which extend across the sides 387.

A plurality of contact pins are slidably mounted upon and through the insulation plates 390 and 392. These contact pins are divided into two groups consisting of a plurality of pins 394 forming one of the groups and a plurality of pins 395 forming the second group. These groups may be distinguished from each other by examining Figs. 78 and 82. The pins 394 are complementary to and engageable with group selector contact plates 396 and the secondary pins 395 are complementary to and engageable with a type selector contact plate 397. These plates will be later on further defined.

Each of the contact pins 394 and 395 are resiliently urged in one direction. For this purpose a collar 398 is mounted on each of said contact pins at a position to the back of the front plate 392. Springs 399 are coaxially

mounted on the contact pins 394 and 395 and act between these collars 398 and the back plate 390 for urging the contact pins forwards to positions in which the collars 398 engage the front plate 392. Vertical insulation strips 400 are mounted upon the sides 387 and extend to the back of the frame 385. These vertical insulation strips 400 are provided with horizontal slots 401 extended inwards from their back edges. Horizontal pairs of insulation strips 402 and 403 are mounted across each of the slots 401. The cable 364 extends along the sides of the insulation strips 400 and the lead from this cable 364 pass through the spaces between the insulation plates 402 and 403 and selectively connect with terminals 405 on these strips. There is one wire for each of the contact pins 394 and 395. Each of the springs 399 has, at its back end, an extension 406 which connects with one of the terminals 405 and in this way each of the wires of cable 364 is connected with one of the springs 399 of the contact pins 394 and 395 so as to electrically connect with said contact pins 394 and 395.

A cover 407 normally extends across the front of the frame 385. This cover 407 has inclined top and bottom portions 408, and sides 409. Hinge lugs 410 are mounted upon one of the sides 409 of the cover 407 and the adjacent side 387 of the frame 385 in order to hingedly mount the cover 407 in position on frame 385. A pair of stop blocks 411 are mounted on the side 387 which is remote from the side 387 provided with the hinges 410. These stop blocks 411 are complementary to and engageable with stop blocks 412 mounted upon the side 409 of the cover 407 which is also remote from the hinge 410. These stop blocks 411 and 412 are secured in position with screws 413. The stop blocks 411 are accurately held in correct positions by dowel pins 414 which have their outer ends set inwards from the faces of the blocks 411. The stop blocks 412 are provided with complementary dowel pins 415 which accurately locate the blocks 412 and which project slight distances from the faces thereof. These dowel pins 415 are adapted to engage in the small spaces of the blocks 411 adjacent the free ends of the dowel pins 414. The blocks 411 and 412 and the dowel pins 414 and 415 act to accurately set the cover 407 upon the frame 385.

The cover 407 is associated with means by which it may be latched in its closed position. This means includes lugs 416 mounted upon the frame 407 and provided with keeper openings 417. Brackets 418 are mounted upon the frame 385. Studs 419 are rotatively mounted upon the brackets 418. Hooks 420 are free to turn on the studs 419 and are engageable in the openings 417. Each stud 419 is provided with a handle 421 by which it may be turned. The hooks 420 are connected with each other to move in unison by a connecting rod 422. The ends of the connecting rod 422 are pivotally connected with the hooks 420 by screws 423. The studs 419 are provided with projecting pins 424 which are engageable with the heads of the screws 423 for lifting the hooks 420. The studs 419 are provided with small eccentrics 425 capable of pulling the hooks 420 slightly rearwards for tightly locking the cover 407 in position. In Fig. 64 the latching means is shown in its closed position. In this position the eccentrics 425 are forcing the hooks 420 towards the right so as to firmly hold the cover 407 in position. The handles 421 may be turned clockwise to the positions shown in Fig. 69. While the handles 421 are thus rotated the eccentrics 425 will be turned to move the hooks 420 slightly towards the left. This releases the hooks 420 so that they are free to be lifted. The pins 424 strike the heads of the screws 423 for lifting the hooks 420 to the open position as illustrated in Fig. 69. Now the cover 407 is free to be hinged open. In the closed position of the cover 407 the handles 421 are individually operated to individually cause the eccentrics 425 to move the hooks 420 slightly towards the right to lock the cover 407 firmly in its closed position.

A tape guide back plate 430 is slidably mounted on said frame 385. This plate 430 is provided with a plu-

rality of openings 394' and 395' through which the contact pins 394 and 395 pass. The back plate 430 is an insulation plate. It is provided with a top angle iron 431 to close the space between it and the frame 385 when viewed from the top. The back plate 430 is slidably guided by several dowel pins 432. The dowel pins 432 are mounted upon the sides 397 and extend through the edge portions of the back plate 430. The sliding motion of the back plate 430 is limited by several screws 433. These screws 433 are mounted on the sides 387 and engage through openings along the sides of the plate 430. The side portions of the back plate 430 are reinforced with strips 434. The screws 433 have heads which engage the strips 434 and limit motion of the back plate 430 in one direction. Expansion springs 435 are mounted on the screws 433 and act between the back plate 430 and the sides 387 for urging the back plate 430 outwards against the heads of the screws 433. Several tape guiding strips 436 and 437 are mounted upon the strips 434 and serve to guide the edge portions of the perforated tape 438 which moves across the tape guiding back plate 430 during the operation of the machine.

The cover 407 is provided with a tape guiding front plate 440 which is normally opposed to the back plate 430. This tape guiding front plate 440 is provided with a plurality of apertures 394' and 395' through which the contact pins 394 and 395 may pass. The front plate 440 has cutouts 441 and 442 along its sides into which the guide strips 436 and 437 may engage in order to properly guide the tape 438 between the plates 430 and 440. The front plate 440 is also provided with a top angle iron 443. The front plate 440 is fixedly mounted in position upon the cover 407 by a plurality of stationary studs 445 which are mounted upon the sides 409 of the frame 407 and which engage the inside face of the front plate 440. A movable plate 446 is mounted in between the front plate 440 and the frame 407. This movable plate 446 supports an insulation frame 447 which carries the said group selector contact plates 396 and type selector plate 397 on its face adjacent said front plate 440. Headed screws 448 are mounted upon the movable plate 446. The heads of these screws 448 engage the outside face of the front plate 440. A plurality of dowel pins 449 are mounted upon the frames 407 and pass through openings in the movable plate 446 and the front plate 440. When the cover 407 is moved to its closed position the dowel pins 432 and 449 are in end contact with each other. The back plate 430 is provided with openings 450 into which the headed screws 448 may extend. The front plate 440 is provided with openings 451 into which the headed screws 433 may extend.

The movable plate 446 which carries the group selector contact plates 396 and the type selector contact plate 397 is associated with eccentric means for forcing said contact plates 396 and 397 towards the tape guide plates 430 and 440 for engaging the contact pins 394 and 395 with the said contact plates 396 and 397. This eccentric means includes shafts 454 rotatively mounted across the sides 409 of the frame 407. Wheels 455 are fixed on the shafts 454. These wheels 455 are eccentrically mounted on said shafts. The wheels 455 comprise eccentric hub portions 456, ball bearings 457, and outer rims 458. Flexible strips 459 are mounted on the movable plate 446. These strips 459 are free at their centers. At their ends the strips 459 are mounted upon blocks 460 which in turn are mounted on said movable plate 446. The central portions of the strips 459 engage against the adjacent sides of the eccentric wheels 455. The outer sides of the eccentric wheels 455 are contacted by plates 461. These plates 461 are supported upon posts 462, which in turn are mounted on the movable plate 446. In Fig. 66 the eccentric wheels 455 are shown in their left positions in which the various plates between the frames 385 and 407 are separated.

When the eccentric wheels 455 turn through 180° to the positions shown in Fig. 70, the various plates between the frames 385 and 407 will be forced together.

In the separated positions of these various plates referred to above the tape 438 is free to pass through the control unit. When the various plates are contacting, as shown in Fig. 70, the contact pins 394 and 395 will engage the tape 438 and those contact pins which align with openings in the tape 438, will extend through the tape 438 and contact the contact plates 396 and 397, as indicated in Fig. 77. The eccentric wheels 455 are operated by an electric motor drive. Each of the shafts 454 are provided with worm wheels 465 which are engaged by worm pinions 466. These worm pinions 466 are fixed upon a shaft 467 rotatively mounted in bearings 468 mounted upon one of the sides 409. The shaft 467 is provided with a worm wheel 469 which meshes with a worm pinion 470 upon the shaft of a drive motor 471. This drive motor is mounted upon a support plate 472 which is mounted across the sides 409 of the frame 407. The motor 471 is capable of indirectly driving the shafts 454 so as to operate the eccentric wheel 455.

Cams 475, 476, 477, 478, and 479 are fixedly mounted on one of the shafts 454. These cams respectively operate switches 480, 481, 482, 483 and 484. The functions of these cams and switches will be covered further on in this specification.

The frame 385 is mounted on a base 485. This base is provided with a roll support comprising a pair of opposed stationary brackets 486 and 487. A pivot 488 is mounted on a bracket 487. A retractable pivot 489 is mounted on a bracket 486. This retractable pivot 489 slidably extends through a tubular housing 493 mounted on the bracket 486. The outer end of the pivot 489 is provided with a head 491 by which it may be moved. A spring 492 is mounted in the tube 493 and normally maintains the pivot 489 in its extended position. A roll of tape 438 may be mounted between the pivots 488 and 489, as indicated by the dot and dash line 438 in Fig. 64. A tape guiding roll 493 is mounted upon brackets 494 mounted on the sides 387 of the frame 385. This guiding roll 493 is located at the bottom of the tape guide plates 430 and 440.

A bracket 498 is mounted on the top of the frame 385. This bracket 498 has a bottom 499 and side arms 500. A drum 501 is mounted between the side arms 500 in a position in which the tape 438 may engage over the top thereof. This drum 501 is provided along its side with pins 502 for engaging corresponding openings 503 formed along the edge portions of the tape 438. The shaft of the drum 501 is provided with a worm wheel 504 which is engaged by a worm pinion 505 on a rotatively mounted shaft 506. This shaft 506 is rotatively supported in bearings 507 mounted upon one of the sides 500. The shaft 506 is provided with another worm wheel 508 engaged by a worm pinion 509 on the shaft of a drive motor 510. The motor 510 is mounted upon the bottom 499.

A guide roller 511 is mounted across the sides 500 adjacent the top portion of the drum 501. The tape 438 is intended to engage under this roller 511. The tape then continues and engages upon a roll 438' which is mounted between a rotative peg 512 mounted on one of the walls 500, and a retractable peg 489 mounted on the other wall 500. This retractable peg 489 engages through a tubular member 490 mounted on the other wall 500. The outer end of peg 489 is provided with a head 491. Within the tubular member 490 there is an expansion spring 492. The outer end of peg 512 is provided with a wheel 513 which is engaged by a belt 514 engaging over a wheel 515 mounted on the shaft of the drum 501. Rotations from the drum 501 will be transmitted by the belt 514 to drive the peg 512, which in turn will wind up the roll of tape 438'.

An inverted U-shaped bracket 518 is pivotally mounted across the top of the bracket 498. This bracket 518 has

a top 519 and sides 520. Pivot screws 521 pivotally support the sides 520 upon the walls 500. A counter-pressure roller 522 is mounted upon the top of the bracket 518 and is engageable against the drum 501 in order to hold the tape 438 against the drum so that the perforations 503 maintain engagement with the pins 502. The bottom end portion of the arms 520 connect with tension springs 523. These tension springs 523 pass through openings 524 formed in the walls 500. The springs 523 are connected between the walls 500 and the sides 520 in order to resiliently engage the roller 522 against the drum 501.

A latch is provided for holding the bracket 518 in an inoperative position. This latch comprises a leaf spring 526 mounted on the inner face of one of the walls 500. The leaf spring 526 is fixedly held at one end by a screw 527. The other end of leaf spring 526 is provided with a peg 528 which passes through an opening in the side walls 500 and which is engageable in a complementary opening 529 formed in one of the sides 520 of the bracket 518. A stop bracket 530 is attached to the wall 500 adjacent the free end portion of the spring 526. This stop bracket 530 is secured in place with a screw 531. The top portion 532 of bracket 530 is spaced slightly from the spring 526 so that the spring 526 may be flexed towards the bracket 530 to disengage the peg 528 from the opening 529. A push button 533 is mounted on the spring 526 and extends through an opening in the side 500 and is adapted to be pushed inwards to flex the spring 526 in order to open the latch. Fig. 67 illustrates the bracket 518 held by the latch. The button 533 may be pressed to release the bracket 518.

The tape guide front plate 440 is provided with a small rectangular opening 535 at a point below the contact plates 396 and 397. This opening 535 is arranged along one side of the tape guide plate 440 outside of the area of the openings 395'. A line stop cam 536 is slidably mounted in this opening 535. This cam 536 has an inclined projecting edge portion 537 which is adapted to engage the tape 438. The tape guide plate 430 is provided with an opening 538 complementary to the opening 535 into which the line stop cam 536 may extend when said tape guide plates are in contact with each other. The line stop cam 536 controls a switch 539 mounted on a block 540 attached to the tape guide plate 440. The tape 438 is provided with a line of slots 541 along one edge portion through which the line stop cam 536 may extend. Normally, the tape 438 maintains the line stop cam 536 in depressed condition in which the switch 539 is closed. However, each time that the tape 438 reaches a point in which one of the openings 541 aligns with the cam 537 the latter element is freed and the resiliency of the switch 539 forces the cam 536 through the opening 541 of the tape 438 so that the switch 539 becomes opened. The tape 438 is moved in a direction so that it engages against the inclined end 537 of the cam 536 for depressing the cam in order to close the switch 539.

The primary contact pins 394 and the secondary contact pins 395 are arranged in groups in which each group comprises primary contact pins 394 and secondary contact pins 395 in straight transverse lines across the tape 438. There is one of these transverse groups for each type support ring 38. In Figs. 81 and 82 two of the type support rings 38 and two of the groups of the contact pins 394 and 395 have been illustrated in full lines. However, it should be understood that forty of these groups are required, if the machine is to operate with forty characters to the line, and other numbers are required if there are to be other numbers of characters to the line. The tape 438 has cooperating groups of openings 542 through which the contact pins 394 and 395 may extend, there being two openings for each group of these pins, namely, one opening for one of the primary pins 394 and one opening for one of the secondary pins 395. The opening for the contact pin 394 will control the selection of the type face,

that is, it will control the stopping of a type support ring 38 in one of the sectors of ring 38 bearing one face of type. The one opening for the pin 395 will control the stopping of the type support ring 38 at one particular piece 5 of type of the selected type face. The tape 438 is formed with a plurality of the openings 542 along its length and the openings 542 between each adjacent pair of the line stop openings 541 will control the position of stopping of all the type support rings 38. For each type support ring 38, the brushes 366' and 365' thereof, are individually connected with the pins 394 of one transverse group of pins by leads 543. For each type support ring 38 the group of stationary contacts 360 are individually connected by leads 544, with the individual contact pins 395 of its 15 corresponding transverse group of contact pins. The primary contact pins 395 for each type support ring 38 are associated with means for connecting them with their respective group selector brushes 365. This means includes leads 545 connecting the rail contact 363' with 20 alternate brushes 365 and a lead 546 connecting the contact rail 364' with the remaining alternate brushes 365.

In the particular design of the machine as illustrated on the drawings there are six brushes 365 to represent six different faces of type for each type support ring 38. 25 These six brushes 365 are arranged approximately equal distances from each other, approximately 60° apart. The group of stationary contacts 360 for each type support ring 38 is arranged in an angular space of about 60°. The contact rails 363' and 364' also extend through angular distances of 60°. With this arrangement each one of the six primary contact pins 394 of each group for each type support ring 38 will control one of the brushes 365, in conveying an electric current to one of the contacts 360. This will be better understood by noting 30 that for each ring 38 one primary contact pin 394 of a transverse group of pins may pass through one opening 542 of the tape 438 and engage one of the contact plates 396. A current may now flow from the contact plate 396 through one of the leads 543 to one of the brushes 365' or 366'. From one of these brushes current will flow to one of the rails 363' or 364'. From this particular rail current may flow to three alternate brushes 365, but two of these brushes will be in an area outside of the area of the group of stationary contacts 360. There 45 will be but one hot brush 365 for this particular area of the contacts 360 which will represent the selected type face of the particular type support ring 38. This particular hot brush 365 will start passing across the contacts 360 until it reaches that contact 360 which is connected with the secondary contact pin 395 engaging through the second opening 542 of the two openings for each type support ring 38. This particular contact pin 395 will connect with the contact plate 397 for closing the circuit through the particular contact 360.

50 It should be recalled that each type support ring 38 is driven by an electric motor 80. Each motor 80 is controlled in the following way. A main switch 550 controls the supply of electric current from some source to a first lead 551 and a return lead 552. The first lead 551 connects with a lead 553 which includes in series the switch 554 of a relay 555. The lead 553 then continues and connects with one terminal of each of the motors 80. A return lead 556 connects with the other terminal of each motor 80 and passes through a switch 557 of a relay 558. The lead 556 continues from the switch 557 to a stationary contact 559. This stationary contact 559 is engaged by a movable contact 560 mounted on the movable core 355 of the solenoid 356 of the particular type ring 38 driven by a particular motor 80. 55 From the movable contact 560 a lead extends to the return lead 552. A resistance 561 shunts each switch 557 at a point which connects the stationary contact 559 in parallel with the switch 557 and resistance 561. The first lead 551 also connects in series with a switch 563 60 of a relay 564 and then continues through the coil of

the solenoid 356 to a contact 565 also mounted on the movable core 355 of the solenoid 356 of said particular type ring 38. For each solenoid 356 there is a stationary contact 566 cooperative with movable contact 565 through which the circuit continues through the switch 567 of a relay 568. From the switch 567 the circuit continues to the return lead 552. The first lead 551 and return lead 552 supply current to a transformer 569. The first lead 570 from the transformer 569 connects in series with a switch 571 of a relay 572. The switch 571 connects with the contact plate 397. For each type ring 38, a lead 573 from one contact plate 396 connects with the coil of its relay 568 and then through a second switch 574 of said relay 568. From this second switch 574 the circuit continues through the coil of the relay 558 and through a second switch 575 of the relay 558. This second switch 575 controls the connection of the coils of the relays 558 and 563 in parallel. This second switch 575 is also engageable with a contact 576 connected by a lead 577 with a tap to the center of the secondary of the transformer 569.

Each stationary group of contacts 369 has several auxiliary contacts 369' to its front. As illustrated in Fig. 81 there are four such additional contacts. Each of the contacts 369' are connected with shunt lines 571' which include a resistance 572'. These shunt lines 571' connect each contact 369' or 369 with the fifth contact further on. The type support rings 38 when driven rotate clockwise with reference to Fig. 81. With this arrangement when a "hot" brush 365 comes along it first engages the contacts 369' and when it is in a position four contacts ahead of the "hot" contact 369, a current will flow through the lead 544 of the "hot" contact 369 but this current will be reduced by one of the resistances 572'.

The circuits used in stopping each motor 89 may be understood from the following: Current from the lead 570 will be supplied through the switch 571, when closed, to the contact plate 397. From the plate 397 the circuit continues through one of the contact pins 395 for each type support ring 38. For each type support ring 38 the current flows from one of the contact pins 395 through one of the resistances 572' and contacts 369' or 369 to the "hot" brush 365 and then through one of the rails 363' or 364' to one of the brushes 365' or 366', through one of the leads 543 and to one of the contact pins 394. The current then continues from the particular contact pin 394 to one of the contact plates 396 to lead 573 through the coils of the relays 563 and 558 to the return lead 589 of the transformer 569. However, the relay 568 is designed to require more current for its operation than is now flowing, so this relay 568 will not be affected and will remain in the position illustrated in Fig. 81. The relay 558 is designed to be affected by the current now flowing so that the switches 557 and 575 are thrown to their second positions. The switch 575 will engage the contact 576 so that current will flow through the tap lead 577. This flow of current will maintain the relay 558 in its thrown position. In the thrown position of the relay 558 the switch 557 was opened and opened the shunt across the resistance 561. Current now flows through this resistance 561 cutting down the flow of current through the electric motor 89 and slowing up the motor 89. Each motor 89, in like manner, therefore drives its type ring 38 at a slower rate of speed.

In a short while the hot brush 365 will make contact with the hot stationary contact 369. Full strength current will now flow through the particular lead 544 so that full current now flows through the coil of the relay 568. This relay is therefore actuated and its switches are thrown to their second position. Switch 567 will now supply the coil of the solenoid 356 with current which will flow from the lead 551 through the switch 563, when this switch is closed, through the coil of the

solenoid 356, through the contact 565 carried by the core 355, the contact 566, the switch 567, and the return lead 552. The core 355 of the solenoid 356 therefore is moved and the brake rack 353 will engage the teeth 47 and lock the type support ring 38 in its selected position. When the switch 574 is thrown to its second position the circuit through the holding relay 558 is opened and this relay will return to its initial position as illustrated in Fig. 81. When the core 355 of the solenoid 356 moved, the circuit through the electric motor 89 was opened at the contacts 559 and 560. The solenoid 356 will maintain its locking position because the circuit through its coil was closed when the core 355 of the solenoid 356 moved to its locking position by the contact 565 engaging contact 573'.

The type setting machine has a second control unit, which is schematically illustrated in Fig. 84, which is for the purpose of controlling the restarting of the type setting machine after the reproduction of a set line of type by any process. For example, the process may be an actual printing process to print from the set line of type, or it may be a photographic process to be used in a photo offset printing process, or it may be a process for the actual production of slugs from the set type, or other process. This control unit has a shaft 575 which is driven by an electric motor 576. The shaft 575 is provided with cams 577' and 578 which respectively control switches 579 and 580. It is intended that the shaft 575 perform a complete revolution of 360° during the printing, photographing or other reproduction of the line of set type. The motor 576 is controlled by an electric circuit including in series a main switch 581 and the switch 582 of a relay 533. The coil 584 of the relay 533 is controlled by the switches 388 and 389. The first lead 589 is connected in series with the coil 584 which is connected in series with the switch 380 which connects to the return lead 570. The cam 577 has one projection 586 which closes the switch 380 to energize the relay 583 in order to start the motor 576 for the printing, photographing or other type copying operation. The cam 578 has one notch 587 which closes the switch 580, which takes over the operation of the relay 583 after the projection 586 releases the switch 380. The circuit may be traced from the lead 589 through the coil 584, through the switch 380, to the return lead 570. When the printing, photographing or other type copying process has been completed the shaft 575 will have turned 360° so that the switch 580 is opened to release the relay 583 in order to stop the electric motor 576.

The electric motor 167 is controlled by a relay 590. This relay 590 has a switch 591 in series with the motor 167 which is electrically connected with the leads 551 and 552. The coil 592 of the relay 590 is connected in series with the switch 579 which is closed by a projection 593 on the cam 577'. The circuit continues from the switch 579 through the switch 372 which is controlled by a pair of projections 594 on the cam 370. These projections 594 are located 180° from each other. The circuit continues from the switch 372 along the lead 595 to a stationary contact 596 which is engageable by a movable contact 597 mounted upon one of the cores 355 of one of the solenoids 356. Each solenoid 356 has a corresponding stationary and movable contact forming a series of switches schematically indicated by the reference numerals 593. The last stationary contact 596 of the series of switches 593 is connected with the return lead 570 of the transformer 569. It should be noted that the relay 590 is therefore controlled by the switches 579, 372 and 598 which are all connected in series. Consequently, when the control unit illustrated in Fig. 84 is in its starting position, the position illustrated, and the shaft 264 is in the position illustrated in Fig. 83, so that the switch 372 is closed, the electric motor 167 will be started immediately upon the closing of the last switch

598. In other words, after all of the solenoids 356 are energized and their cores have been raised, then the electric motor 107 will start operating.

The relay 555 controls the operation of the motors 80. The coil 600 of the relay 555 is connected in series with the bottom section 601 of the switch 378. The switch 378 is controlled by one niche 602 formed in the cam 374. When the cam shaft 102 of the type setting machine is in its starting position, the position illustrated in Fig. 83, the switch 378 engages the niche 602 so that the switch section 601 is closed. A circuit now exists from the lead 589 through the coil 600, the switch section 601 to the return lead 570. The relay 555 is therefore energized and its switch 554 is closed so that the motors 80 are in operative conditions. As soon as the shaft 102 turns, the switch section 601 will be opened and the motors 80 will stop. The switch 378 has a top switch section 603 which closes when the switch section 601 opens. This top section 603 takes over the duty of the top switch section 604 of the switch 481. The switch 481 is operated by the cam 476 which has one projection 605 to operate the switch 481. The top switch section 604 functions to close the relay 564. The circuit may be traced from the lead 589 through the coil 606 of the relay 564 through the switch section 604 to the return lead 570. When the switch section 604 opens, the relay 564 may still be energized because another circuit exists from the lead 589 through the coil 606 of the relay 564 and through the switch section 603 to the return lead 570. The switch 481 also has a lower switch section 607 which controls the relay 572. The relay 572 has a coil 608 which is connected in series with the first lead 589, the switch section 607, and the return lead 570. It will therefore be seen that when the bottom switch section 607 is closed the relay 572 will be energized so that the switch 571 is closed and an electrical potential is supplied to the contact plate 397.

The motor 270 is controlled by a relay 610. This relay has a switch section 611 which is connected with the current supply leads 551 and 552. The switch 611 is controlled by the coil 612 which is connected in series with the central movable contact arm 613 of switch 373. The contact arm 613 is provided with a projection 614 which engages the cam 371. This cam has a high section 615 and a low section 616. The switch 373 has a bottom switch section 618 and a top switch section 619. The switch 373 is electrically connected with the switch 379. Said switch 379 has a central movable contact 620 provided with a projection 621 engaging the cam 375 which has a high section 622 and a low section 623. The switch 379 has a bottom switch section 624 and a top switch section 625. The movable contact arm 620 of the switch 379 is connected with the return lead 570. As illustrated in Fig. 83 the bottom switch sections 618 and 624 are closed. In this position the motor 270 is inoperative. When the cam 375 is turned around so that the high section 622 opens the switch section 624 and closes the switch section 625, a circuit will be closed through the coil 612, the bottom switch section 618, and the top switch section 625 which causes the motor 270 to operate until the cam 371 turns around so that the high cam section 615 throws the switch 373 to open the bottom section 618 and close the top section 619. Now a circuit exists through the coil 612, the top switch section 619, and the bottom switch section 624, provided of course that the bottom switch section 624 is reclosed by the cam 375.

The cam 376 controls the starting position of the type setting unit. This cam 376 has a high spot 626, a low spot 627, and the remainder of the cam surface is neutral. The switch 381 operated by the cam 376 has a top switch section 628 and a bottom switch section 269. The high spot 626 closes the top switch section 628, while the low spot 627 closes the switch section 629. In the remaining portion of the cam 376, the switch 381 is in a neutral position in which the switch sections 628 and 629 are both

open. The electric motor 471 of the tape control unit is controlled by a relay 632. This relay has a coil 633. The coil 633 is connected in series with the bottom section 629 of the switch 381. The circuit may be traced from the lead 589 through the coil 633 and the lead 634 which connects through the switch section 629 to the lead 570. It will thus be seen that the cam 376 is capable of operating the relay 632.

The high spot 626 of the cam 376 represents the starting position of the type setting machine and this position is checked by the cam 477. This cam 477 has one niche 636 which controls the opening of the switch 482. A circuit exists from the lead 589 through the coil 633 and through the switch 483 when this switch is closed to the lead 637 which connects to the return lead 570 through the switch section 628. The circuit from the coil 633 may also pass through the switch 483 when closed, and the switch 482 to the return lead 570. The tape control unit shown in Fig. 82 will cease operation by its motor 471 stopping in the event that the switch 482 opens and the switch section 628 is also opened. In this condition of the machine the tape control unit will not start until the type setting machine reaches the starting position in which the high spot 626 of cam 376 closes the switch section 628.

The electric motors 471 and 510 receive current through the main switch 638. The circuit of the motor 471 includes the switch section 639 of the relay 632, in series. The circuit of the motor 510 includes the switch section 640 of a relay 641, in series. The relay 641 has a coil 642. The relay 641 has another switch section 643 which operates simultaneously with the switch section 640. When current flows through the coil 633 of the relay 632 the motor 471 operates. When current flows through the coil 642 of relay 641 the motor 510 operates. The cam 475 controls the relay 641. This cam 475 has a high spot 645 which is capable of closing the switch 480. When this switch 480 is closed an electric circuit extends from the lead 589 through the coil 642, the switch 480 to the return lead 570. The cam 478 stops the motor 471 at certain times. This is accomplished by two low spots 647 in the cam 478 opening the switch 483. These low spots are 180° from each other. When the switch 483 opens the circuit is opened through the coil 633 of the relay 632 which stops the motor 471. A push button switch 625 shunts switch 483. The motor 471 is started by the cam 479. This cam has one high spot 650 which closes the switch 484. When this switch 484 is closed a circuit will extend from the lead 589 through the coil 633, the switch 484, through the switch section 643 to the return lead 570.

The panel board 340 is also used to support the various relays of the type setting machine. Note particularly the relays 557 and 558 (see Fig. 4). In the tape control unit a panel board 654 is mounted upon the frame 497. This panel board 654 supports the relays 641, 632, and 572. Another panel board 655 supports the switches 480 to 484, inclusive. The main switch 638 is illustrated mounted on the panel board 472.

Fig. 85 is a schematic view indicating the timing of the machine. Particularly it indicates the timing of the various steps taken by the machine in relation to cam shaft 102. The radial lines 1, 10, 14, and 18 indicate positions in which the cam shaft 102 is stationary. The remaining arcuate lines numbered from 2 to 23, excluding the numbers 1, 10, 14 and 18, which have been utilized for the radial lines, indicate the various cam actions which take place in their proper relationship with each other. Some of these actions take place singly, and others simultaneously. Simultaneous actions are indicated by the arcuate lines being in overlapping positions. The arcuate lines 24 indicate rotation of cam shaft 102 between the stopped positions thereof.

The operation of the machine may be understood from the following:

The wiring diagram, namely Figs. 81-84 inclusive,

schematically illustrate the various switches and relays and other parts of the machine at one instant of the operation of the machine at a point in the cycle represented by the radial line 1 in Fig. 85. At this moment the cam shaft 192 is stationary because the relay switch 591 controlling the motor 107 which drives the shaft 192 is open. The relay switch 591 is open because no current is flowing through the relay 590 due to the fact that the series of switches 598 are open. These switches 598 are open when the solenoids 356 are in their down positions so that the type support rings 38 are free to rotate. As illustrated, all the type support rings 38 are being rotated because all of their driving motors 80 are receiving current. This may be understood by first noting that the control unit illustrated in Fig. 82 has at this instant reached a position in which the eccentric wheels 455 have moved the contact plates 396 and 397 against the pins 394 and 395. Those pins 394 and 395 which align with openings 542 in the tape 433 will extend through said openings 542 and in this way make contact with the contact plates 396 and 397. The remaining pins 394 and 395 were merely depressed. The control unit shown in Fig. 82 is at this instant in a stationary position, that is, the circuits to the motors 471 and 510 are open because the relays 632 and 641 controlling these motors are deenergized so that they seek the positions in which the relay switches thereof are illustrated. The printing control unit shown in Fig. 84 at this moment is also inoperative because its relay 583 is not receiving current and its switch 582 is open. The motor 270 of the type setting machine is also inoperative because its controlling relay 610 is not receiving current at this moment. The relays 564 and 555 controlling the solenoids 356 and motors 80 are receiving current and are therefore closed. The relay 555 controls the simultaneous operation of the motors 80, and since this relay is now closed all of the motors 80 are operated. Current is flowing through the coil 600 of the relay. The circuit may be traced from the lead 589 through the coil 600, the closed switch section 601 to the return line 579. The circuit through the coil 606 may be traced from the lead 589 through the coil 606, the closed section 604 of the switch 481 to the return lead 579.

The instant that the contact plates 396 and 397 engaged certain of the pins 394 and 395, certain of the contacts 360 and certain of the brushes 365 became "hot," that is, a current will flow when a "hot" brush 365 touches a "hot" contact 360. The tape 433 has its openings 542 arranged in transverse pairs. Each of these transverse pairs will control a different one of the type support rings 38. The six pins 394 of each ring 38 will control the selection of a particular face of type, and the pins 395 of each ring 38 will control the selection of one piece of type or one type wedge from said selected type face. The rotating type support rings 38 will each come to a stop at a position as controlled by the tape 433 and pins 394 and 395. The action of all of the type support rings 38 is simultaneous, but of course the rings 38 will stop at different moments depending upon their reaching their correct positions. The circuit for stopping the type support ring 38, illustrated at the left in Fig. 81, may be traced as follows: Here it is assumed that the tape 433 has the two openings which control the pins 394 and 395 to this ring 38 at the points which correspond with the heavy lines 543 and 544. An electric circuit now exists from the lead 570 through the switch 571 of the relay 572, which is receiving current because the switch section 607 of the switch 481 is closed. The current flows through the switch 571 to the contact plate 379. From this plate 379 the current may flow through one pin 395 through the resistance 572' to the first contact 360'. At this moment the circuit is open at this point and therefore nothing further happens until the type support ring 38

rotates a little further so that the brush 365 illustrated by the dark lines touches the said first contact 360'. When this occurs the circuit will be closed and current will flow to the particular pin 394 electrically connected with the particular brush 365 which just has made contact with the first contact 360'. From this pin 394 the current will reach the contact plate 396 and flow through the particular lead 573 and through the coils of both relays 558 and 568 of this first type wheel 38. The circuit then continues to the return lead 589. While current flows through both of the relays 558 and 568 only the relay 558 will be affected because it is of a design requiring less current than the relay 568. The resistance 572' cuts the current of the circuit so that a sufficient amount of current flows only to affect the relay 558. The affected relay 558 immediately throws its switches 557 and 575 towards the left. The switch section 557 opens up the shunt circuit across the resistance 561 of the motor circuit 80. Current which up to this point was bypassing the resistance 561 now must flow through the resistance 561 and consequently the motor 80 receives less current and slows down. This particular type wheel 38 is now slowing down preparatory to stopping. The switch section 575 when moved to its second position engaged the contact 576 and closed a holding circuit through the coil of the relay 558 so that the relay 558 maintains its closed position even after the brush 365 moves off the first contact 360'. The holding circuit may be traced from the particular lead 573 through the coil of the relay 568, the switch 574, the coil of the relay 558, the switch 575, to the contact 576 along the lead 577 to the tap connection of the secondary of the transformer 569. A short time later the brush 365 of this first type support ring 38 will reach the first contact 360. This shorts out the resistance 572' so that full current is now flowing through the relay 568. Immediately the switches 557 and 574 thereof assume their second position. The switch section 574 merely opens the circuit through the relay 558 which then returns to its initial position, the position illustrated on the drawing. The switch section 567 closes the electric circuit through the coil of the solenoid 356. This circuit may be traced from the lead 551 through the coil of the solenoid 356 to the contact 565, the contact 566, the switch 567 to the lead 552. The core 355 of the solenoid 356 now moves so as to engage the brake segment 353 against the ring gear 47 of the type support ring 38, which locks this ring 38 in a fixed position. When the core 355 moved to its locking position, the contact 560 disengaged from the contact 559 which opened the circuit through the motor 80 causing the ring 38 to stop. When the core 355 moved to its second position the circuit through the coil of the solenoid 356 was broken by contact 565 disengaging from contact 566. However, a new circuit was made through the coil of the solenoid 356 by the contact 565 engaging the contact 573. Consequently, current continues to flow through the solenoid 356 and brake segment 353 continues to hold ring 38. The above action takes place for each of the type support rings 38. The type support ring 38 illustrated at the extreme right in Fig. 81 is illustrated in a position in which the "hot" brush 365 has engaged the "hot" contact 360 so that full strength current will flow through the relay 568 of said ring 38. However, the relay 568 is illustrated still in its open position since for illustration purposes we are assuming the parts in a position an instant before motion of the relay 568 has taken place. However, it should be noted that the relay 558 is illustrated in its second position. Each time that one of the type support rings 38 comes to a stop a switch 598 thereof is closed. It should be noted that the contacts 597 engage the contacts 596 to close the switches 598. These switches 598 are connected in series and after the last one of these switches 598 has been closed a circuit is

closed through the relay 590 so that the motor 107 starts driving the cam shaft 102. The circuit may be traced from the lead 589 through the coil of the relay 592, the closed switch 579, the closed switch 372, all of the closed switches 598 to the return lead 570.

The cam shaft 102, as illustrated in Fig. 83, is in a position which we may call its "starting" position. In this position the cam 376 is holding the switch section 628 closed. As soon as the cam shaft 102 starts turning in the direction indicated by the arrow, the switch section 628 will open and the switch section 629 will momentarily close as the contact arm of the switch 381 rides down into the cutout 627. The switch 629 will close the circuit through the relay 632 and start the control unit illustrated in Fig. 82 into operation. The control unit will proceed through an approximately 95% portion of its cycle and then will stop and await until the cam shaft 102 again reaches its starting position in which the high spot 626 of cam 376 will reclose the switch section 628.

When the cam shaft 102 turns an angular distance of about 10° the contact arm of the switch 381 will fall into the low spot 627 of the cam 376 and will close the switch section 629 momentarily. The switch section 629 will momentarily close an electric circuit through the coil 633 of the relay 632 so that the switch section 639 closes and starts the motor 471. The circuit may be traced from the lead 589 through the coil 633, the lead 634 through the switch section 629 to the return lead 570. A small turn of the shaft 454 will cause the cam 478 to keep the motor 471 running for at least to the 180° position of the shaft 454. The turn of the shaft 454 causes the cam 478 to close the switch 483. A circuit now exists from the line 589 through the coil 633, the switch 483, the switch 482 to the return line 570. The small turn of the shaft 454 will operate the switch 481 as follows: The projection 605 will release the switch 481 so that both switch sections 604 and 607 open. Switch section 604 releases one circuit through the relay 564 preparing to cut off the current from all of the solenoids 356. The circuit just opened may be traced from the line 589 through the coil 606 of the relay 564 to the open switch 604 which is connected with the return 570. However, the relay 564 remains closed because cam 374 on cam shaft 102 takes over the operation of keeping the relay 564 closed at this time. A slight turn of the cam shaft 102 caused the cam 374 to operate the switch 378 to close the switch section 603. A circuit now exists from the line 589 through the coil 606 of the relay 564 through the closed switch section 603 to the return 570. However, the cam 374 will open the circuit through relay 564 to release all of the solenoids 356 when the cam shaft 102 again reaches its "starting" position and when the control unit of Fig. 82 is in a position with its switch section 604 still open. The switch section 607 of the switch 481 when open, will de-energize the relay 608 causing the switch 571 to open and disconnect the circuit to the contact plate 397.

As the motor 471 operates it drives the shafts 454 so that the eccentric wheels 455 separate the plates 447, 449, and 430 in the control unit. This separation frees the tape 438 from the pins 394 and 395 so that the tape 438 is ready to move. When the shaft 454 reaches a position of about 170° from the position shown in Fig. 82 the projection 645 of cam 475 will close the switch 480 which will cause the electric motor 510 to start functioning. The circuit may be traced from the line 589 through the coil 642 of the relay 641 through the now closed switch 480 to the return line 570. The relay 641 now becomes energized and the switch sections 640 and 643 are thrown to the left. The switch section 640 closes an electric circuit to the motor 510. The motor 510 drives the tape 438 which when moved but a short distance causes depression of the cam 536 which closes the switch 539. This causes the motor 510 to continue operating even though the cam 475 turns so that the switch 480 re-opens.

The new circuit may be traced from the line 589 through the coil 642, through the now closed switch 539 to the return lead 570. The motor 510 will keep operating until the tape 438 reaches its next position in which the next opening 541 aligns with the cam 536. The cam 536 then moves into the opening 541 causing the opening of the switch 539 which causes the motor 510 to cease functioning. Opening of the switch 539 cuts the circuit through the relay 641 which causes the switch sections 640 and 643 to seek the right hand position as illustrated in Fig. 82. The motor 471 is still operating, and when the shaft 454 reaches an angular position 180° from the position shown, the cam 479 will close the switch 484. This switch 484 will cause continued operation of the motor 471 provided that the switch section 643 has reclosed. The circuit may be traced from the line 589 through the coil 633, the switch 484, the switch 643, to the return 570. If the switch 643 is still open it means that the motor 510 is still operating and the tape 438 is still moving. The motor 471 will cease functioning until the switch 643 closes. At the 180° position the eccentric wheels 455 have the contact plates 447, 440 and 430 in their separated positions so that the tape 438 may freely move. When the switch 643 recloses the motor 471 proceeds to drive the shaft 454 to cause the eccentrics 455 to close the plates 447, 440 and 430 so that the contact pins 394 and 395 are engaged through new perforations 542 of the tape 438 to engage the contact plates 397 and 396. The motor 471 keeps operating until the shaft 454 has turned about 350° and then the cam 477 checks to ascertain if the cam shaft 102 of the type setting machine is in its "starting" position. It should be noted that when the shaft 454 turns approximately 350° the cutout 636 of the cam 477 causes the switch 482 to open. This would stop the motor 471 provided the switch section 628 of switch 381 is not closed. The circuit may be traced from the line 589 through the coil 633 of the relay 632 through switch 483 which is closed at this time, along the line 637 to the switch 628 which if closed completes the circuit to the line 570. However, the switch section 628 is open at this time because the cam shaft 102 was recently started and must complete a full revolution, which as yet it has not done. Therefore the control unit illustrated in Fig. 82 stops and waits for the type setting machine to reach the "starting" position of its cycle.

At this point it may be best to assume that the cam shaft 102 has completed a full revolution and has again reached the "starting" position so that we may complete the study of the cycle of the control unit shown in Fig. 82. If the checker cam 477 when opening the switch 482 does not stop the motor 471 because switch section 628 is closed, the motor 471 continues and turns about 10° more to reach the position in which it is illustrated in Fig. 82. When reaching this position cam 478 will stop the motor 471 by opening the switch 483. Simultaneously, cam 476 will cause the switch sections 604 and 607 to close. The switch section 604 will energize the relay 564, as already explained, in order to prepare for the closing of circuits through the coils of the solenoids 356 and to later release these solenoids 356 as required. Switch section 607 will energize relay 572 to close the switch 571 and thus supply current to the contact plate 397. The control unit of Fig. 82 is now in its original position at which point we started explanation of its operation. When the cam shaft 102 started turning from its "starting" position the cam 374 threw the contact arm of switch 378 to close switch section 603 and to open switch section 601. Switch section 601 when open prevents all of the motors 80 from running until the cam shaft 102 again reaches its "starting" position. The circuit may be traced from the line 589 through the coil 600 of the relay 555 and the now open switch 601 which connects with the lead 570. When the switch 601 was opened the circuit was broken through the coil 600 and

the switch section 554 was opened and opened the electric circuit to all of the motors 80. When the control unit of Fig. 82 is in the position as illustrated the push button switch 625 may be momentarily closed to start the control unit and cause it to complete an entire cycle and thus move tape 438 to its next position. An operator of the machine may in this way skip sections of the tape 438.

While the tape control unit of Fig. 82 is operating, the type setting unit is simultaneously functioning. The various steps of operation and the operation of the various cams may be best understood by re-examining Fig. 85 and noting that the arcuate lines thereof represent angular periods during which certain cam operations take place. It should be noted that certain of these arcuate lines overlap, which represents simultaneous operations of certain of the cams. For easy reference the 24 lines, or steps, indicated in Fig. 85 will be catalogued to give the various cam operations represented thereby:

- 1.—Cam shaft 102 stationary while the type rings 38 rotate and stop at desired points.
- 2.—Type and type wedges pushed out of stopped type rings.
- 3.—Pushed out type turned upright.
- 4.—Type push-out comb pulled back.
- 5.—Type push-back comb pulled down.
- 6.—Type aligners released for aligning type to true vertical positions.
- 7.—Type holders pushed into top slots in type and type wedges.
- 8.—Wedge stretch-out comb pushed into position.
- 9.—Type aligners lifted.
- 10.—Type carrier bar pulled across table top—cam shaft 102 stationary.
- 11.—Wedge closing mechanism pushed up.
- 12.—Wedges closed.
- 13.—Type clamped.
- 14.—Cam shaft 102 stationary while reproduction of type takes place.
- 15.—Type clamp opened.
- 16.—Type wedges opened.
- 17.—Wedge closing mechanism pulled down.
- 18.—Type carrier bar moved back—cam shaft 102 stationary.
- 19.—Type push-back comb pushed up.
- 20.—Type holders pulled out of type.
- 21.—Type turned sidewise.
- 22.—Type pushed back into rings 38.
- 23.—Type push-back comb pulled back.
- 24.—Periods in which cam shaft 102 rotates.

Step #2.—Type pushed out

The cams 191 cause the rods 94 to be moved towards the right, in relation to Figs. 23 and 23a. This motion is transmitted to the arms 91 which in turn move the type push out comb 83 from its left position shown in Figs. 23, 23a and 26 to its right position shown in Figs. 46 and 47. The teeth 35 of the comb 83 pass through the radial slots 41 of the type support rings 38 and move the type 54 and type wedges 55 which are aligned with the type carrier bar 57 to positions extended through the rectangular openings 115 of the disc 114. The ball bearings 117 grip the rear ends of the type and type wedges and hold them in horizontally extended positions over the type carrier bar 57.

Step #3.—Type turned upright

The cams 139 pivot the arms 134 downwards causing the bell cranks 139 to turn so as to move the slide 125 which in turn moves the bar 121. The pins 123 on the bar 121 pivot the discs 114 through 90° so that the rectangular openings 115 are moved from the horizontal position shown, for example, in Figs. 32 and 35, to the vertical position shown in Figs. 53 and 60. Since the

type and type wedges are held by the balls 117 they are correspondingly turned to a substantially vertical position, as illustrated in Fig. 60. In this substantially vertical position the notches 63 in the type 54 and type wedges 55 are engaged upon the type holding strip 61. Simultaneously, the lugs 67 of the type 54 and type wedges 55 are engaged to the front of the bar 66. The type and type wedges are thus supported against longitudinal movement though they are free to move transversely along the length of the type carrier bar 57.

Step #4.—Type push-out comb pulled back

The cams 101 now move the rods 94 back to their original positions. This motion is transmitted by the arms 91 to move type push out comb 83 back to its original position, the position at the left as illustrated in Figs. 23, 23a and 26.

Step #5.—Type push-back comb pulled down

The cams 155 now move the type push back comb 142 from its up to its down position. More particularly, the cams 155 pivot the arms 158 downwards, which in turn move the type push back comb 142 downwards on the vertical guide pins 152. In Fig. 27 the type push back comb 142 is shown in its raised position, while in Fig. 54 it is illustrated in its down position.

Step #6.—Type aligners released for type aligning

At this time it is necessary that the type 54 and type wedges 55 be moved to truly vertical positions since they are merely in upright positions, as illustrated in Fig. 60. This is accomplished by the cams 192. These cams 192 pivot the bell cranks 188, 189 so as to cause the rods 187 to move upwards. The rods 187 move the arms 186 upwards which pivot the rod 182 clockwise in respect to Figs. 39 and 41. This causes the pins 183b to move upwards off of the bottom ends of the slots 183a. The springs 183c therefore move the type aligners 183 downwards. These type aligners have beveled bottom ends 184 which engage the top portions of the type 54 and type wedges 55 and move them into truly vertical positions. In Fig. 52 the type aligners 183 are shown in their released positions in which they engage the type and type wedges.

Step #7.—Type holders pushed into type

The cams 221 pivot the arms 218 upwards (see Fig. 24) in order to pivot the arms 215 downwards, which in turn moves the rods 214 downwards. When the rods 214 move downwards they free the rods 210 so that these rods are free to move downwards. The springs 209 thereupon move the rod 203 downwards, which moves the accordion like leaf springs 199 downwards so that the prongs 197 move down and engage into the slots 196 in the top of the type 54 and type wedges 55. In Fig. 40 the rod 203 is shown in its raised position, while in Fig. 51 it is shown in its lowered position.

Step #8.—Wedge stretch-out comb pushed into position

The wedge stretch-out comb 232 is normally in a lowered position, as for example, shown in Figs. 28 and 32. Now, the cams 245 act to pivot the arms 248 upwards, see Fig. 28, so as to push the rods 250 upwards, which in turn push the wedge stretch-out comb 232 into its raised position. The cams 245 immediately move the arms 248 back into their lowered positions because the cam sections 253 are relatively small angularly. However, as soon as the wedge stretch-out comb 232 assumes its raised position, the springs 255 extend the bolts 254 so that the reduced end portions 256 engage upon the keeper plates 258 which latches the wedge stretch-out comb 232 in its raised position. In the raised position of this comb 232 the pegs 234 engage into the slots 231 of the type wedges 55. Those pegs 249 which strike type 54 are merely depressed. Those pegs 234 which en-

gage the slots 231 act to hold wedge sections 227 of the type wedges 55 stationary so that the wedges 55 become extended when the carriage 56 moves forwards. At this time it may be well to point out that after the carriage 56 has moved a certain distance forwards the reduced end portions 256 of the bolts 254 will ride off of the keeper plates 258 so that the wedge stretch-out comb 233 is released. The springs 238 immediately move the comb 232 downwards to its original position. This causes the pegs 234 which engaged the slots 231 to come out of these slots. Whereupon, the type wedges 55 are not extended any further. This represents the fully extended position of the type wedges. Figs. 52 and 53 illustrate the wedge stretch-out comb 232 in its raised position. Figs. 32 and 34 illustrate it in its lowered position. The stop strip 244 acts to hold the type 54 and type wedges 55 from being moved upwards by the pegs 234 when the type stretch-out comb 233 is moved to its raised position.

Step #9.—Type aligners lifted

It is necessary that the type aligners 183 be lifted free from the type 54 and type wedges 55 before the carriage 56 may move to its forward position. The cams 192 now take care of this operation. The cam sections 194 move the bell cranks 188, 189 back to their original positions in which the rods 187 are moved downwards and turn the arms 186 so that the rod 182 is turned counterclockwise. The pins 183b now engage the bottom ends of the slots 183a and lift the type aligners 183 against the action of the springs 183c.

Step #10.—Type carrier bar carried across table top

Now that the type aligners 183 have been moved free of the type 54 and type wedges 55, the carriage 56 is ready to be moved to its front position so that the type carrier bar 57 correspondingly moves the type and type wedges. The carriage 56 is moved forwards by the arms 260 which are connected eccentrically with the wheels 263. The wheels 263 are driven by a motor 270 which is now started up by the cam 375. At this moment the cam 375 has turned to a position in which the high section 622 of the cam lifts the projection 621 so as to close the switch section 625 and open the switch section 624. When the switch section 625 is closed the relay 610 will be energized. The circuit may be traced from the lead 589 through the coil 612 of the relay 610, through the closed switch 618, through the closed switch 625 to the return lead 570. Upon the slightest turn of the motor 270 the cam 370 will stop the motor 107 so as to stop rotation of the cam shaft 102. The cam 370 takes care of this operation as follows: A slight turn of cam 370 causes the switch 372 to open. This opens the circuit through the motor 107. This circuit has been previously traced. The motor 270 is now operating and the carriage 561 is being moved to its front position.

During the motion of the carriage 56 to its front position, the wheels 272 move in the tracks 273 and move the compression slides 271 together. These slides 271 compress the bellow construction composed of the leaf springs 199. When the leaf springs 199 are compressed the prongs 197 move the type 54 and type wedges 55 together to a position at the center of the table top 35 between the ends 275 of the tracks 273. Fig. 55 illustrates the type 54 and type wedges 55 in this contracted position.

When the carriage 56 reaches its extreme forward position the cams 370 and 371 have turned 180°. The cam 370 at this point recloses the switch 372 which restarts the motor 107. The cam 371 reaches a position in which the high section 615 moves the contact arm 613 so that the switch section 618 is opened and the switch section 619 is closed. Opening of the switch section 618 stops the motor 270. Closing of the switch section 619 prepares for the later restarting of the motor 270 by the cam 622.

Step #11.—Wedge closing mechanism pushed up

Now that the cam shaft 102 is again rotating the cam 300 is turning so that the cam track 301 moves the wedge closing mechanism up. Particularly, the cam 300 lifts the web 303 which lifts the vertical slide 295 from the lowered position shown in Figs. 5 and 38 to the raised position shown in Fig. 56. When the wedge closing mechanism reaches its raised position the connector 285 connects with the type wedges 55. This is done by the flange 286 engaging the slots 231 of the type wedges 55.

Step #12.—Wedges closed

The cams 313 now function to move the horizontal slide 291 of the wedge closing mechanism forwards. The cam tracks 312 pivot the arms 307 forwards so that the slots 310 in said arms which engage the pintles 309 move the horizontal slide 291 forwards. Since the yoke 288 is mounted on the horizontal slide 291 it is moved forward and compresses the springs 290. These springs 290 supply the necessary pressure for forcing the wedge sections 227 of the type wedges 55 forwards and in this way expanding the wedges 55 to justify the line of type between the wall portions 276 of the compression slides 271.

Step #13.—Type clamped

Now that the type wedges 55 have been expanded the cams 329 act to pivot the arms 326 and 324 to move the collars 321 down upon the rods 320. This compresses the springs 322 which in turn moves the rods 320 downwards and pivots the arms 319, causing the rod 317 to turn under a resilient force. The cams 316 on the rod 317 engage against the center of the clamping bar 66, slightly flexing this bar 66 and causing this bar 66 to clamp the type 54 and type wedges 55 firmly upon the type carrier bar 57. The type is now ready to be reproduced by any known process. This process may be direct printing, photographing, etc., as already discussed in the object portion of this specification.

Step #14.—Reproduction of type

An instant after the type 54 and type wedges 55 have been clamped for the reproduction operation, the cam shaft 102 reaches a position in which the cam 377 closes the switch 380. This closes an electric circuit through the relay 583. The circuit may be traced from the lead 589 through the coil 584 of the relay 583, the switch 580 and the return lead 570. The relay 583 controls the electric motor 576 which now starts operating. The motor 576 drives the shaft 575. This immediately causes the cams 577 and 578 to respectively open the switch 579 and close the switch 580. The opening of switch 579 opens the circuit to the relay 590 which controls the electric motor 107. The motor 107 now stops, causing the cam shaft 102 to stop rotating. The switch 580 controls the relay 583 and causes the electric motor 576 to continue operating until it has turned 360°. The circuit through the switch 580 may be traced from the lead 589 through the coil 584, the switch 580 and the return lead 570. The electric motor 576 may be a timing motor operating for a certain length of time which is sufficient to complete the reproduction of the line of type. The motor 576 may control the reproducing operation in other ways. For example, the motor 576 may actually operate the mechanism which does the reproducing of the line of type, and this mechanism may be so geared up, that the reproduction cycle is completed when the shaft 575 makes one complete revolution. It should be noted that the type setting unit of the machine is now idle, awaiting completion of the reproduction of the line of type. As soon as the shaft 575 has completed a full revolution the cam 575 recloses the switch 579 and causes the electric motor 170 to restart and

drive the cam shaft 102. Simultaneously, the cam 578 controls the opening of the switch 580 which controls the stopping of motor 576.

Steps #15 to #23

Now that the cam shaft 102 is again rotating the mechanical cams thereof continue their operations which may easily be understood by following Steps 15 to 23, inclusive. At Step 15 the cams 329 now function to indirectly turn the rod 317 back into its original position in which the cams 316 release the type clamping bar 66. This frees the type 54 and type wedges 55. The type wedges 55 are opened during Step 16 in which the cams 313 pivot the arms 307 back to their original positions so that the yoke 288 engage the heads 289 of the rods 287 and moves the connector 285 rearwards, causing the flange 286 to pull the wedge sections 227 rearwards, and in this way open the wedges.

The wedge closing mechanism is now moved down in Step 17, preparatory to moving the carriage 56 back to its original position. The cam 300 operates to move the web 303 down which in turn moves the vertical slide 295 down in order to move the wedge closing mechanism to its down position. At this point the cam shaft 102 is stopped and the wheels 263 are operated to move the carriage 56 back, during Step 18. Cam 622 has now reached a position in which the projection 621 will move off the high section 622 so that the switch 625 is opened and the switch section 624 is closed. Closing of the switch section 624 closes the circuit through the relay 610 which restarts the motor 270. Opening of the switch section 625 prepares for the later restarting of the motor 270. As soon as the motor 270 is restarted the cam 370 causes the opening of the switch 372 which operates the relay 590 and stops the motor 107 and so stops the cam shaft 102. The motor 270 continues functioning until the wheels 263 have turned 180° during which time the carriage 56 will be returned to its original position.

During the rearward motion of the carriage 56 the wheels 272 ride along the cam tracks 273 and cause the compression slides 271 to move back to their original positions upon the end portions of the type carrier bar 57. The compression slides 271 in this way release the leaf springs 199 which then expand back to their original positions, causing the prongs 197 to spread out the type 54 and type wedges 55. Just as the carriage 56 reaches its rear position the prongs 197 will engage between the teeth of the comb 280 which will accurately position the prongs 197 in relation to the type support rings 38. As soon as the wheels 263 have completed the 180° rotation which returned the carriage 56 to its starting position, the cam 370 closes the switch 372. This causes operation of the relay 590 which restarts the motor 170 causing the cam shaft 102 to start turning. Cam 371 now causes motor 270 to stop. The mechanical cams now continue their operation. The type push back comb 142 is pushed up in Step 19, the cams 155 moving the arms 158 which in turn move the slide 147 to accomplish the pushing up of the type push back comb. The type holders, namely, the prongs 197 are pulled out of the type 54 and type wedges 55 in Step 20. The cams 221 perform this function by moving the arms 218 and 215, which in turn raise the rods 214. These rods 214 are now aligned with the rods 210 which lift the rod 203 carrying the leaf springs 199. The type 54 and type wedges 55 are now turned back to their horizontal positions in Step 21. The cams 139 perform this function by moving the arms 134 which move the bell cranks 130, in turn moving the slide 125. Since the slide 125 engages the lug 128 of the bar 121, this bar is moved. The bar 121 provided with the pins 123 which pivots the discs 114 so that the rectangular openings 115 are turned back from their vertical positions to their horizontal positions.

The type 54 and type wedges 55 are now ready to be pushed back into the type support rings 38, in Step 22.

Cams 163 perform this function. The tracks 164 of the cams 163 cause the rods 167 to move towards the left (see Fig. 9) which in turn move the rods 172 towards the left. Since the rods 172 are connected with the horizontal slide 145 of the push back comb 142, the comb 142 is operated so that the teeth 144 push back the type 54 and type wedges 55 into the slots 41 of the type support rings 38. The push back comb 142 is immediately pulled forward to its forward position in Step 23, by operation of the said cams 163.

The cam shaft 102 has now completed a complete turn and the cams 374 and 376 respectively operate the switches 378 and 381. Cam 374 causes motion of the contact arm of switch 378 so that switch section 603 is opened and switch section 601 closed. When switch section 603 opens, the circuit is opened through the relay 564 causing the switch 563 to open. This opens the circuit through all the coils of the solenoids 356. This causes all of the cores 355 to return to their starting positions, freeing the type support rings 38 for rotation. All of the motors 80 now start up because their circuits have been closed through the contacts 560 engaging the contacts 559. All of the type support rings 38 are now rotating. When switch section 601 closed the relay 555 was energized causing the switch 554 to close, which is necessary for the motors 80 to operate. The high spot 623 of cam 376 closed the switch section 628 which is necessary to signal the restart of operation of the control unit illustrated in Fig. 82. It will be recalled that the said control unit stopped when cam 477 opened switch 482. The control unit now operates, and about a 10° turn on shaft 454 places said shaft in the position shown in Fig. 82. Cam 476 now closes switch section 604 which energizes relay 564 closing switch 563, and the other sequence of operation ensues as already described. The machine is now in its original position and the cycle is ready to repeat.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described the invention, what is claimed as new and desired to secure by United States Letters Patent is:

1. In a type setting machine, a plurality of type support rings, each provided with slots oriented to accommodate a plurality of type and type wedges flat on their sides and normal to the plane of the ring, means for rotatively supporting said rings in adjacent positions on a horizontal axis, a horizontal type carrier bar positioned across one of the sides of said rings, means for rotating each of said rings, means for stopping each of said rings in a selected position in relation to said bar in order that any piece of type and type wedge carried by each of said rings may be stopped at said bar, means for engaging the type and wedges stopped at said bar on to said bar, means for righting said type and type wedges, means for movably supporting said type and wedges on said bar in order that said type and wedges may be moved together into printing position, means for moving said type and wedges together to a predetermined width, and means for expanding said wedges in order to wedge said type in said predetermined space in order to make said type ready for printing in a justified condition.

2. A type setting machine as defined in claim 1, including springs mounted on said type and type wedges and engaging the walls of said slots for accomplishing the releasable holding of said type and wedges in said slots.

3. A type setting machine as defined in claim 1, in which said means for rotatively supporting said rings includes a stationary drum engaging through said rings, and rollers mounted on said rings and engaging said drum.

4. A type setting machine as defined in claim 3, includ-

ing rollers mounted on the sides of said rings and engaging adjacent said rings.

5. A type setting machine as defined in claim 1, in which said means for rotating each of said rings includes a ring gear coaxially mounted on each of said rings, and a drive means for each ring, each drive means having a driven gear meshing with said ring gear of said ring being driven by said drive means.

6. A type setting machine as defined in claim 5, in which each drive means also includes a worm wheel coaxially connected with the said driven gear, a worm pinion meshing with said worm wheel, a flexible shaft connected coaxially with said worm pinion, and a motor connected to drive said flexible shaft.

7. A type setting machine as defined in claim 1, in which said means for stopping each ring includes a ring gear coaxially mounted on each ring, and a segmental gear brake shoe for each ring gear and engageable with its associated ring gear.

8. A type setting machine as defined in claim 7, including a solenoid operated lever system for each of said brake shoes.

9. A type setting machine as defined in claim 1, in which said means for engaging the type and wedges on to said bar includes a type push out comb within said rings, and means for moving said comb forwards to push said type and type wedges stopped at said bar to a position over said bar.

10. A type setting machine as defined in claim 9, including means for moving said type and type wedges over said bar to a position on said bar.

11. A type setting machine as defined in claim 1, in which said means for movably supporting said type and wedges on said bar includes a type holding strip on said bar, slots in said type engaging said type holding strip, a plurality of leaf springs connected in accordion fashion and supported above said bar and having prong portions engageable in slots in the top of said type.

12. A type setting machine as defined in claim 11, including means for lowering said leaf springs for engaging said prongs in said slots and lifting said leaf springs for disengaging said prongs from said slots.

13. A type setting machine as defined in claim 12, in which said means for moving said type together includes slides on the end portions of said bar, and cam means for moving said slides together.

14. A type setting machine as defined in claim 1, in which each wedge comprises a pair of slidably connected wedge sections, and said means for expanding said wedges including means for moving the wedge sections of each wedge relative to each other.

15. A type setting machine as defined in claim 1, including means for returning said type and wedges back to their original positions in the slots of said rings.

16. A type setting machine as defined in claim 1, including means for clamping said type firmly in said predetermined space for firmly holding the type during printing.

17. A type setting machine as defined in claim 16, in which said means for clamping includes a clamping bar positioned above said type, and cam means for flexing said clamping bar against said type.

18. In a type setting machine, a frame including a table top, a plurality of adjacent axially aligned type supporting rings provided with type and type wedges positioned sideways on said rings, a carriage slidably mounted on said table top and provided with a horizontal type carrier bar normally positioned across one of the sides of said rings, wheels rotatively mounted on said frame on an axis parallel to the axis of said rings, rods eccentrically connected with said wheels and with said carriage for moving said carriage to a forward position on said table top and back again, a cam shaft rotatively mounted on said frame at a point beneath said table top and extending parallel to the axis of said rings, a type push out comb

within said rings for pushing type and type wedges from said rings and on to said type carrier bar, means for operating said type push out comb including cams on said cam shaft, means for righting said type and type wedges after they have been pushed out of said rings, a type push back comb movably mounted on said table top to the front of said type carrier bar for pushing type and type wedges back on to said rings from said type carrier bar, means for turning said type and type wedges upon their sides, and means for operating said push back comb after the type and type wedges have been turned upon their sides, including cams on said cam shaft.

19. A type setting machine as defined in claim 18, in which the means for righting the type and type wedges includes controlling cams on said cam shaft.

20. A type setting machine as defined in claim 18, including means for holding said type and type wedges in true vertical positions.

21. A type setting machine as defined in claim 20, in which said last named means for holding the type and type wedges in true vertical positions includes holding prongs engaging in slots in the top of said type and type wedges.

22. A type setting machine as defined in claim 18, including slides on said type carrier bar, and wheels mounted on said slides and engaging a cam track formed in said table top for moving said slides on said type carrier bar to compress and release said type and type wedges on said type carrier bar when said carriage moves to its forward position and back again.

23. A type setting machine as defined in claim 18, including means for lowering said type push back comb beneath said table top for permitting said carriage to move over said table top.

24. A type setting machine as defined in claim 23, in which said last mentioned means includes operating cams on said cam shaft.

25. In a type setting machine, a frame, a plurality of adjacent axially aligned type support rings provided with type and type wedges disposed upon their sides in said rings, said rings being rotatively mounted on said frame, a carriage slidably mounted on said frame and provided with a horizontal type carrier bar normally positioned across one of the sides of said rings, means for turning said rings to selected positions in relation to said bar in order that any piece of type and type wedges carried by said rings may be stopped at said bar, means for engaging the type and type wedges stopped at said bar on to said bar, means for righting and movably supporting said type and type wedges on said bar in upright positions in order that said type and wedges may be moved together into printing position, means for moving said carriage forward to a printing position, means for moving said type together into printing position during motion of said carriage to its printing position, means for moving said carriage back to its starting position adjacent said rings, means for spreading said type to its original position on said bar during motion of said carriage to its starting position, and means for returning said type and wedges to their original positions on said rings.

26. A type setting machine as defined in claim 25, in which said frame includes sides and a drum mounted between said sides, and said rings being rotatively mounted on said frame by being rotatively mounted on said drum.

27. A type setting machine as defined in claim 25, in which said carriage is slidably mounted on said frame with slides on said carriage engaging tracks on said frame.

28. A type setting machine as defined in claim 25, in which means for turning said rings to selected positions includes a control unit operated with a perforated tape.

29. A type setting machine as defined in claim 25, in which said means for engaging said type and type wedges on said bar includes a push out comb for pushing the type and type wedges out of said type support rings, and means for operating said push out comb.

30. A type setting machine as defined in claim 29, including a type holding strip on said bar, and means for engaging said type and type wedges on to said type holding strip.

31. A type setting machine as defined in claim 25, in which said means for movably supporting said type and type wedges on said bar includes a plurality of leaf springs movably supported above said bar and having prongs engageable in slots in said type and type wedges.

32. A type setting machine as defined in claim 31, in which said leaf springs are connected with each other in accordion fashion.

33. A type setting machine as defined in claim 25, in which said means for moving said carriage forwards includes a pair of rotatively mounted wheels, arms eccentrically connected with said wheels and connected with said carriage, and means for turning said wheels.

34. A type setting machine as defined in claim 25, in which said means for moving said type together includes slides on the ends of said type carrier bar, and means for moving said slides together.

35. A type setting machine as defined in claim 33, in which said means for moving said carriage back to its original position includes said wheels, said arms, and said means for turning said wheels.

36. A type setting machine as defined in claim 31, in which said means for spreading said type includes said leaf springs.

37. A type setting machine as defined in claim 25, in which said means for returning said type to its original position includes a type push back comb, and means for operating said comb to push the type and type wedge from said bar back on to said rings.

38. In a type setting machine, a frame, a plurality of adjacent type support rings rotatively mounted on said frame, a carriage slideably mounted on said frame and provided with a horizontal type carrier bar normally positioned across one of the sides of said rings, means for moving type from said rings to positions on said type carrier bar, compression slides on the ends of said type carrier bar, and means for moving said compression slides together in order to move said type together into printing position, said frame including a table top provided with a cam track, said means for moving the compression slides together including wheels mounted on said slides and engaging said cam track.

39. In a type setting machine, a frame, a plurality of adjacent type support rings rotatively mounted on said frame, a carriage slideably mounted on said frame and provided with a horizontal type carrier bar normally positioned across one of the sides of said rings, means for moving type from said rings to positions on said type carrier bar, compression slides on the ends of said type carrier bar, and means for moving said compression slides together in order to move said type together into printing position, said type carrier bar being provided with a type holding strip, said means for moving type from said rings on to said type carrier bar including means for turning said type in order to engage notches in said type on to said type holding strip.

40. A type setting machine as defined in claim 39, in which said means for turning said type includes rotatively mounted discs having openings through which said type may engage, and means for turning said discs.

41. In a type setting machine having type wedges which are open at times and require closing and reopening, a connector for connecting with the rear ends of the type wedges, a horizontal slide, horizontal rods slidably mounted upon said slide and supporting said connector, resilient means acting between said horizontal slide and said connector for resiliently transferring a forward motion of said horizontal slide to said connector, a vertical slide supporting said horizontal slide, means for moving said vertical slide upwards to a position in which

said connector engages said type wedges, and means for moving said horizontal slide forwards for closing said type wedges and rearwards for opening said type wedges.

42. A type setting machine as defined in claim 41, in which said connector includes an upwardly extending flange engageable in slots formed in the bottom of said type wedges.

43. A type setting machine as defined in claim 41, including heads on the free ends of said rods for limiting forward motion of said connector.

44. A type setting machine as defined in claim 41, in which said resilient means comprises springs coaxially mounted on said rods.

45. A type setting machine as defined in claim 41, in which said means for moving said vertical slide upwards includes a web on the bottom of said vertical slide, and a cam connected with said web.

46. In a type setting machine, a plurality of rotatively supported type supporting rings having radial slots with type and extending from their inside diameters completely through to their outside diameters, a horizontal type carrier bar positioned across one of the sides of said rings, means for rotating each of said rings, means for stopping each of said rings in a selected position in relation to said bar in order that any piece of type carried by each of said rings may be stopped at said bar, a plurality of normally open switches one for each of said rings, means for closing one of said switches for each of said rings which is stopped, means for pushing the type stopped at said bar on to said bar and including a motor drive controlled with a relay having a controlling coil, and an electric circuit connecting said switches and said coil in series.

47. A type setting machine as defined in claim 46, in which said means for stopping each of said rings includes a ring gear coaxially mounted on each of said rings, a solenoid for each ring gear, and said solenoids having cores with rack brake section segments engageable with said ring gears when energized.

48. A type setting machine as defined in claim 47, in which said switches are operated by the cores of said solenoids.

49. In a type setting machine, a plurality of rotatively supported type support rings, a ring gear coaxially attached to each of said rings, means for rotating said rings including a drive motor for each of said rings, a type carrier bar positioned across one of the sides of said rings, means for stopping said motors for stopping rotation of each of said rings in selective positions in relation to said bar in order that any piece of type carried by said type support rings may be stopped at said bar, said means for stopping rotation of said rings including a solenoid for each ring having a core provided with a rack brake section engageable with said ring gear of said ring for latching said ring in its stopped position, means for engaging the type stopped at said bar on to said bar and including a first cam shaft and a motor for driving said cam shaft, means for moving said bar to a printing position including a second cam shaft and a motor for driving said

second cam shaft, means for readying said type for reproduction at said printing position including a third cam shaft and a motor for driving said third cam shaft, a switch for each of said solenoids closed upon operation of said solenoids, cams on said second and third cam shafts, switches controlled by said cams so that said switches are closed when said second and third cam shafts are in certain positions, a relay for controlling said motor which drives said first cam shaft, and a circuit connecting said relay in series with said switches for controlling starting of the motor which drives said first cam shaft when all of said switches are in their closed positions and stopping of said motor which drives said first cam shaft when said second and third cam shafts move out of said certain positions.

50. A type setting machine as defined in claim 49, including a relay for controlling said solenoids, another relay for controlling said motors which drive said rings, a cam on said first cam shaft, and switches controlled by said last named cam and connected with said last two mentioned relays for releasing said solenoids and restarting the motors which drive said rings when said first cam shaft reaches a certain position.

51. A type setting machine as defined in claim 49, including a relay for controlling said motor which drives said third cam shaft, another cam on said first cam shaft, another cam on said third cam shaft, and switches controlled by said two last mentioned cams for starting the motor driving said third cam shaft when said first cam shaft reaches a certain position and stopping the motor which drives said third cam shaft when said third cam shaft reaches a certain position.

52. A type setting machine as defined in claim 49, including a relay for controlling said motor which drives said second cam shaft, additional cams on said first and second cam shafts, and switches controlled by said additional cams and controlling said relays for operating said motors which drive said first and second cam shafts at certain different times.

53. A type setting machine as defined in claim 49, in which said means for stopping said rings includes a tape operated control unit having a fourth cam shaft, and a motor for driving said fourth cam shaft, a drive for the tape of said tape operated control unit and a motor for

said drive, relays for controlling said last two mentioned motors, switches for controlling said relays, and cams on said fourth cam shaft operating said last named switches for starting and stopping said last two mentioned motors at certain positions of said fourth cam shaft.

54. A type setting machine as defined in claim 53, including a checker cam on said fourth cam shaft, a start of operation cam on said first cam shaft, and switches controlled by said last two mentioned cams for controlling the operation of the motor which drives said fourth cam shaft.
